CENTRALIZED TRAFFIC CONTROLLING
SYSTEM FOR RAILROADSNeil D. Preston and Thomas J. Judge, Rochester,
N. Y., assignors to General Railway Signal
Company, Rochester, N. Y.

Application April 14, 1933, Serial No. 666,182

23 Claims. (Cl. 177—353)

This invention relates to centralized traffic controlling systems for railroads, and more particularly pertains to the communication part of such systems.

5 By means of the centralized traffic controlling system contemplated by the present invention, the switches and signals at field stations along a railroad system are placed under the supervision of an operator at a control office and the 10 condition of such switches and signals, together with various other traffic conditions, are transmitted to the control office to provide the operator with such information as may be necessary for the proper governing of train movements.

15 The present invention more particularly relates to a centralized traffic controlling system, wherein the supervision of the traffic governing devices and the indication of their conditions is accomplished over a communication system having 20 only two line wires. These two line wires serve to connect the control office with each of the field stations.

The apparatus at the control office and at each field station is organized to be responsive to different series of impulses applied to the two line wires and arranged in distinctive combinations, in accordance with the character of the messages desired to be transmitted and in accordance with the station to or from which such 30 messages are to be transmitted. Each of these series of impulses causes the apparatus at the control office and at the field stations to operate through what is termed a cycle of operations.

More specifically, a battery or other suitable 35 source of current is located at the control office and also another similar source of current is located at the last field station of the system. Thus, the operator may cause the transmission of a series of positive and negative impulses in 40 various combinations from the source located in the control office to accomplish what is termed a control cycle of operations. Likewise, any field station may automatically cause the transmission of a series of positive and negative impulses 45 in various combinations from the source located at the end field station to accomplish what is termed an indication cycle of operations.

The impulses transmitted from the control office are of substantially equal duration and are 50 separated by substantially equal time spaces, while the impulses transmitted from a field station are made long or short in various combinations, being separated by substantially equal time spaces.

55 Step-by-step means located at the control office and at each field station operate in response to the application of impulses irrespective of their character. During a control cycle one of two distinctive messages or controls may be 60 transmitted on each step by reason of the dis-

tinctive character (polarity) of the corresponding impulse applied to the line circuit. During an indication cycle choices of four distinctive messages or indications may be transmitted on each step by reason of the distinctive character 5 (polarity and duration) of the corresponding impulse applied to the line circuit. In other words, it is possible to transmit controls with a choice of two on each step of a control cycle and to transmit indications with a selection of either 10 one choice of four or two choices of two each, on each step of an indication cycle.

Other features of novelty embodied in the present invention reside in the manner in which the field stations are prevented from transmitting 15 indications when the control office is transmitting controls and the manner in which only one field station is effective to transmit indications when the control office is not transmitting, irrespective 20 of the number of field stations which may have new indications to transmit at the beginning of a particular cycle of operations.

A further feature of the present invention resides in the manner in which the timing characteristics are determined in a positive and direct manner. 25

These characteristic features of the present invention, thus briefly stated, will be explained more in detail in the following description of one embodiment of the invention and various other 30 characteristic features, functions and advantages of a system embodying this invention will be in part pointed out and in part apparent as the description progresses.

In describing the invention in detail, reference 35 will be made to the accompanying drawings, in which similar parts throughout the several views are designated by similar reference characters, generally made distinctive either by reason of distinctive exponents representative of their location or by reason of preceding numerals representative of the order of their operation, and in which:—

Fig. 1 illustrates in a diagrammatic manner 45 the line circuits and apparatus associated therewith in a system embodying the present invention;

Figs. 2A and 2B, when placed end to end in the order named, illustrate the apparatus and 50 circuits of a typical control office arranged according to the present invention;

Figs. 3A and 3B, when placed end to end in the order named, illustrate the apparatus and 55 circuits employed at a typical field station in accordance with the present invention.

These drawings illustrate a system having a plurality of field stations and a control office. For convenience in the description, the number of field stations has been assumed to be four, 60

although in actual practice a smaller or larger number could obviously be provided.

With reference to Fig. 1, a control office, an intermediate field station and an end field station with their interconnecting line circuits are indicated. The control office circuits are shown in detail in Figs. 2A and 2B, while the intermediate field station circuits are shown in detail in Figs. 3A and 3B. Since the last or end field station is substantially identical with an intermediate field station, with the exception of the added means included within the dotted rectangle of Fig. 3A designated "End station", the details of the end field station have not been shown in a separate drawing.

Although the embodiment of the present invention illustrates the first or intermediate field station as having only a single switch and its associated signals, it should be understood that the invention is not limited to the control of only one switch and its signals at any field station but it may be extended for any desired number arranged in any suitable track layout.

For the purpose of simplifying the illustrations and description, the various parts and circuits have been shown diagrammatically and certain conventional illustrations have been employed, the drawings having been made more with the purpose in mind of making it easy to understand the principles and mode of operation of such a system, than with the idea of illustrating the particular construction and arrangement of parts that would probably be employed in actual practice. Thus, the relays and their contacts are illustrated in a conventional manner and symbols are used to indicate connections to the terminals of batteries, or other suitable sources of electric current, instead of showing all of the wiring connections to these terminals.

The symbols (+) and (−) are employed to indicate the positive and negative terminals respectively of suitable batteries or other sources of direct current. The symbol (CN) is employed to indicate a center or intermediate tap of a particular battery or source of current indicated by the (B+) and (B−) symbols with which it is associated. Those circuits connected to the terminal designated (CN) may have current flowing in one direction or the other, depending upon the particular terminal (B+) or (B−) of the source used in combination with this indicated intermediate tap.

Control office equipment.—The control office equipment includes a biased-to-neutral, polar line relay F which repeats the polar impulses applied to the line by battery OB. An office battery selecting relay OBS of the neutral type is normally deenergized to supply current from battery OB to the line circuit while the system is at rest. When relay OBS is up, the line circuit can be energized only from the field battery FB⁴ at the end field station, assumed to be the fourth station.

The particular polarity applied to the line circuit, either while the system is at rest or while it is in operation for the transmission of controls, is determined by a pole changing relay PC. While the system is at rest, or in a so-called period of blank, relay PC is normally supplied with (−) potential for supplying (−) potential to the line circuit from the office battery OB. When the system is in operation, relay PC is positioned by a particular polarity during each deenergized period of the line circuit, 75 in accordance with the message to be trans-

mitted, so as to determine by its position the polarity of the following impulse applied to the line circuit. Relay PC is of the two position polarized type, so that its contacts remain in the positions to which they are last actuated by reason of a suitable magnetic stick type arrangement.

Irrespective of the polarity with which the line circuit is energized after the system is started through a cycle, the quick acting line repeating relays 1FP and 2FP repeat each energized and each deenergized condition of the line relay F. In order that the cycles of operation may be distinctively marked off, slow acting line repeating relays SA and SAP are provided, which, when once energized at the beginning of a cycle, remain energized throughout the cycle, irrespective of the brief deenergizations of the line circuit between the several impulses.

A suitable step-by-step means is employed being specifically embodied in a stepping relay bank including relays 1V, 2V, 3V, 4V and 5V together with a half step relay VP. The half step relay is caused to shift its position upon each energization of the line circuit, while the stepping relay bank is caused to take one step following each energization, that is, during the deenergized period between the successive impulses applied to the line circuit.

The control impulses are suitably time spaced and measured by impulsive relay E, impulse repeating relay EP and the actual response of the stepping relay bank in the control office. The maximum length indication impulses (long) are time spaced and measured by the impulsive relay E, the repeating relay EP, an impulse prolonging relay EPT and the actual response of the stepping relay bank in the control office. The minimum length indication impulses (short) are time spaced and measured by the impulsive relay E and the actual response of the stepping bank at the field station which is transmitting the indications.

The control office also includes a lock-out relay LO and a slow acting repeating lock-out relay LOP for purposes hereinafter pointed out in connection with the lock-out features of the system.

The transmitting and receiving equipment located in the control office is made available for effective use by the operator, by providing a suitable control machine having mounted thereon a miniature track diagram of the actual track layout in the field, together with the control levers, buttons and the like which are manually operable to obtain the desired transmission of controls. As typical of such a control machine, a miniature track switch ts, a switch machine control lever SML, and a signal control lever SGL have been shown, these devices being associated with the corresponding traffic controlling devices at the assumed first intermediate field station illustrated in Figs. 3A and 3B.

The control machine preferably has a starting button SB associated with each group of control levers associated with a particular field station, so that, when the control levers for that station are properly positioned in accordance with the positions to which it is desired that the corresponding traffic controlling devices shall be operated, the starting button SB may be depressed thereby causing the transmission of suitable controls to the corresponding field station.

Instead of showing the actual circuits and means associated with the several starting but-

tons of such a system for accomplishing the initiation of the system and allowing the transmission of controls to only one station at a time, such control has been merely indicated. The means 5 usually provided to obtain these results includes a storing relay such as relay SR¹, and a code determining relay such as relay CD¹, one of each for each starting button such as SB. The relays SR¹ and CD¹ for a station group of control levers 10 are so interlocked with the corresponding relays SR² and CD² for other stations, that only one code determining relay can be energized at any one time, irrespective of the number of storing relays which are energized. This is because the 15 starting buttons may be actuated at any time, which fact is stored by the corresponding storing relay, but only one of the storing relays can be effective to energize its corresponding code determining relay, so that only one station code call is 20 transmitted at a time.

Such an arrangement of code determining relays, actuated one at a time either by a starting button such as starting button SB, or by the movement of an associated control lever, has 25 been completely shown in prior applications, such for example as in the pending application of N. D. Preston et al., Ser. No. 455,304, filed May 24, 1930, corresponding to Australian Patent 1,501 of 1931. It is believed, however, that the above discussion of these SR and CD relay functions is 30 sufficient for an understanding of the operation of the present invention.

Also, located on the control machine are suitable indicator lamps, such as lamps N and R for 35 indicating the normal and reverse positions of the track switch TS¹ in the field, when illuminated, and for indicating the unlocked condition of that track switch when both lamps are unilluminated. An indicator lamp OS indicates, when 40 illuminated, the occupied condition of the associated detector track section in the field.

These indicator lamps, as well as other type indicators, are controlled by suitable indication storing relays, such as relays 1IR, 2IR and 3IR, 45 which are of the two position polarized type. A group of these indication storing relays are associated with each control panel allotted to a field station and are rendered effective to receive the indications transmitted whenever the corresponding station is allowed to transmit its indications.

Whenever a field station is conditioned to transmit, it first transmits its code call which is registered in the control office by suitable pilot 55 relays, such as pilot relays 1PT and 2PT. At the end of the transmission of the station code, the pilot relays are in position to select the proper station storing relay, such as relay ST assumed, associated with the station illustrated in Figs. 60 3A and 3B.

The control office includes a plurality of control code sending buses 101, 102, 103, 104, and 105 which are energized in accordance with the position of the code jumpers and control levers for 65 controlling the selection of a station and the transmission of controls thereto.

Indication code receiving buses 131, 132, 133, 134, and 135 are energized in accordance with those indications which are transmitted from a 70 field station by impulses distinctive for their polarity, while indication buses 121, 122, 123, 124, and 125 are energized in accordance with those indications which are transmitted from a field station by impulses distinctive for their duration. 75 Other devices and apparatus include suitable

code jumpers, buses, overload protection and such other means as may be considered adjuncts to a system of this type, but which need not be considered in their specific form for an understanding of the present invention.

Intermediate field station equipment.—With 5 reference to Figs. 3A and 3B of the accompanying drawings an intermediate field station, more specifically considered as the first field station, has been shown as typical of all intermediate field stations. This first field station includes a track switch TS¹ which is operated by a switch machine SM¹ of any suitable type, such for example as disclosed in the patent to W. K. Howe, Patent No. 1,466,903 dated September 4, 1923. The 10 switch machine may, if desired, be provided with a dual control selector, as disclosed for example in the pending application of W. K. Howe, Patent No. 1,852,573, filed April 10, 1929 so as to permit the 15 manual operation of the track switch.

The position of the track switch is repeated 20 by the usual switch repeating relay WP¹ of the polar neutral type. This relay is preferably controlled by a polarized circuit including suitable point detector contacts or switch box contacts 25 (not shown) so that the relay is energized with one polarity or the other depending upon the normal or reverse extreme positions of the track switch, and so that it is deenergized whenever the track switch is unlocked or is in operation.

The track switch has associated therewith the usual detector track section having a track battery and a track relay T¹ included in a normally energized track circuit.

The traffic over the track switch is governed 35 in an eastbound direction by signals 1A¹—1B¹ for governing traffic over the main track or onto the turn-out track respectively, while traffic in a westbound direction is governed by signals 2A¹—2B¹ for allowing the passage of traffic over 40 the main track or off the turn-out track respectively. The signals 1A¹ and 1B¹ have associated therewith a signal repeating relay 1M¹ which is normally energized while both of these signals 45 are at stop, but whenever either of these signals is in a clear or proceed position, this relay is deenergized. Similarly, the signals 2A¹ and 2B¹ have associated therewith a signal repeating relay 2M¹ which is energized with both of these signals at-stop, but which is deenergized whenever 50 either of these signals is in a clear or proceed position. Although these signals 1A¹—1B¹ and 2A¹—2B¹ have been illustrated as being of the 55 semaphore type, it is to be understood that they may be of the light signal type or any other suitable type for governing traffic in accordance with the usual practices.

Although approach track sections have not been 60 illustrated in the drawings as associated with the track switch TS¹, such approach track sections are preferably employed, having associated therewith suitable annunciator track relays such as relays 1AT¹, 2AT¹, and 2BT¹. The relay 1AT¹ may be considered as associated with an approach track section in advance of the signals 1A¹—1B¹, 65 the relay 2AT¹ may be considered as associated with an approach track section in advance of the signal 2A¹, and the relay 2BT¹ may be considered as associated with an approach track section in advance of the signal 2B¹.

The communication part of the system includes, 70 besides the line relay F¹, a quick acting line repeating relay FP¹ of the neutral type which repeats, throughout each cycle of operation, the energized condition of the relay F¹ irrespective 75

of the polarity with which it is energized, while a slow acting line repeating relay SA^1 is energized at the beginning of each cycle of operation and is maintained picked up until the end of that cycle.

5 The field station is provided with a bank of neutral stepping relays $1V^1$, $2V^1$, $3V^1$, $4V^1$, and $5V^1$, together with a half step relay VP^1 . This bank of neutral stepping relays takes one step for each deenergized period of the line circuit 10 during a cycle, each step being taken in synchronism with the corresponding step at the control office. However, the stepping operation at each station is discontinued as soon as that field station fails to be selected for reasons hereinafter pointed out. The half step relay shifts its position upon each energized period of the line as long as the step-by-step operation at that station continues.

20 For the purposes of lock-out, so as to permit only a single station or the control office to transmit during any one cycle, a lock-out relay LO^1 and a selecting relay S^1 are provided, these relays being responsive to the particular conditions of initiation imposed upon the line circuit 25 at the beginning of each cycle. A lock-out repeating relay LOP^1 is associated with the lock-out relay LO^1 , for reasons hereinafter to be explained.

30 A relay P^1 is provided for pulsing the line circuit in accordance with certain of the indications to be transmitted, while a pole changing relay PC^1 is provided for determining the polarity of the impulses in accordance with certain other 35 of the indications to be transmitted.

35 For the purpose of storing any change in conditions which may occur in the traffic controlling devices to be indicated, a change relay CH^1 and a change repeating relay CHP^1 are provided. In the event that a particular traffic controlling 40 device is of such a character that the condition to be indicated is transient or temporary, a suitable storing relay may be provided, such as illustrated by the relay TR^1 associated with the track relay T^1 .

45 Each station equipment is provided with station code receiving relays, which are responsive to the station code calls transmitted over the line circuit for completing selecting circuits so long as the particular code call transmitted 50 corresponds to the code call assigned to that station. Any station may be made responsive to any particular code call of which the system is capable of transmitting by the proper positioning of its station selecting code jumpers. These station 55 code receiving relays for the first intermediate field station, include relays $1ST^1$ and $2ST^1$ which are of the two position polar magnetic stick type.

The controls transmitted for the traffic controlling devices in accordance with the position 60 of the levers in the control office are received by suitable two-position polarized relays preferably of the magnetic stick type, which in turn govern their associated devices. For example, 65 the relay SMR^1 is responsive to the position of the control lever SML and this relay governs the actuation of the switch machine SM^1 to normal or reverse positions. Similarly, the signal relay SG^1 and the direction relay DR^1 are responsive to the position of the signal lever SGL 70 and serve to govern the signals $1A^1$ — $1B^1$ and $2A^1$ — $2B^1$, which control has been merely indicated by a dotted line. This indicated control of the signals is understood to include suitable approach locking, suitable automatic block sig-

nalling control and such other adjuncts to a centralized traffic control system, as may be required to accomplish the usual protection for the movement of trains, all of which has been more specifically set forth in the pending application of S. N. Wight, Ser. No. 120,423, filed July 3, 1926.

5 Each intermediate field station includes a resistor such as R^1 which is of a value dependent upon the distance of that field station from the field battery FB^4 . The line circuit includes, 10 during a certain period at the beginning of each indication cycle of operation, only the line wire up to the station nearest the end of the system which has indications ready to transmit, and a resistor such as R^1 at such station must be provided to limit the current flow in the line thus decreased in length, in order that the proper current value may be maintained in the line relays. The particular value of these resistors is 15 determined in accordance with the usual engineering practices.

20 Each field station includes a group of control code receiving buses, such as buses 201 , 202 , 203 , 204 , and 205 which are energized in accordance 25 with the controls received from the control office.

25 Also, indication code sending buses 231 , 232 , 233 , 234 , and 235 are energized in accordance with 30 those indications which are transmitted from the field station by impulses distinctive for their polarity, while the indication code sending buses 221 , 222 , 223 , 224 , and 225 are energized in accordance 35 with those indications which are transmitted from the field station by impulses distinctive for their duration.

35 *End field station equipment.*—As previously mentioned, the end field station is the same as an intermediate field station insofar as the communication part of the system is concerned, 40 with the addition of the apparatus included within the dotted rectangle of Fig. 3A given the legend "End station", together with the circuit connections coordinating it with the rest of the station.

45 This added apparatus includes a field battery FB^4 and a field battery selecting relay FBS^4 . This field battery selecting relay serves to connect the battery FB^4 into the line circuit during an indication cycle. The control of relay FBS^4 50 is accomplished by the same apparatus provided at other stations through the medium of suitable connecting circuits.

55 In the event that the last field station for receiving controls and transmitting indications is unsuitable for the location of the field battery FB^4 , it is consistent with the present invention to provide an end field station only for the control of the field battery. In other words, only those devices of Fig. 3A which furnish control 60 for the relay FBS^4 are required at such an end station. It is believed unnecessary to illustrate such a station as the means required for the control of relay FBS^4 will be evident from the following description.

65 It is believed that further description will make the invention best understood by setting forth various typical operations of the system.

70 *Operation of the system*

75 The system of the present invention is normally in a condition of rest, but may be initiated into a cycle of operations either from the control office or from any of the field stations whenever

there are new controls or new indications respectively to be transmitted.

Although new controls and indications may occur simultaneously, the system is so arranged 5 that only controls or indications may be transmitted during any one particular cycle. In case new controls and indications become ready for transmission simultaneously, the system is so arranged that the resulting cycle is for the transmission of indications, while the succeeding cycle or cycles, as the case may be, will be for the transmission of the new controls. In other words, indication conditions are superior to control conditions only when such conditions occur 10 simultaneously, but if there are a plurality of stations to receive controls, the operator may cause such controls to be transmitted irrespective of the presence of any new indications which may occur at any one or several of the field stations 15 during such transmission.

While the system is normally at rest, the line circuit is energized with negative potential. Such energization, after a continued deenergization of the line circuit at the end of a cycle of 20 operation, is effective to set the system in readiness for the initiation of a cycle either from the control office or from some field station.

For convenience in describing the present invention, a positive impulse applied to the line 25 circuit in the control office (see Fig. 1) will be considered as current flowing from left to right in the line wire 12, which positions the line relays F (with suitable exponents) to the right, while a negative impulse will be considered as 30 current flowing from right to left in the line wire 12 and the line relays F (with suitable exponents) will be positioned to the left.

When the system is initiated into a cycle of operations, distinctive initiating conditions are 35 set up, depending upon whether the cycle is to be for the transmission of controls or the transmission of indications. If the cycle is to be for the transmission of controls, the current in the line circuit is quickly reversed, that is, the normal negative energization of the line circuit is changed to a positive energization. This positive energization of the line circuit is continued for a predetermined period of time sufficient for all of the 40 field stations and the control office to be in readiness to enter a control cycle, at which time the line circuit is deenergized. For convenience in describing the present invention, the period of time which is required for the reversal of the 45 energization of the line circuit, plus the period of time during which the positive energization of the line circuit is continued, will be considered as the initiating period. In other words, the initiating period extends from the period of rest up to the first continued deenergization of the line circuit.

On the other hand, if an indication cycle is to be initiated, the line circuit conditions throughout the system vary as more specifically pointed out hereinafter, but in general it may be stated 50 that the time before the reversal of the line circuit current, that is, before a positive energization thereof, is of somewhat longer duration, after which the line circuit is energized with positive energy. Similarly in this case, that period of time required for the reversal of the current in the line circuit, up to the first continued deenergization after the application of the first positive energization, is conveniently termed the initiating period.

In brief, each initiating period, irrespective of

the character of the cycle to follow includes a positive energization of the line circuit and the end of such energization is the end of the initiating period. The first deenergization of the line circuit following the initiating period, causes the 5 step-by-step mechanisms at the control office and at the field stations to take the first step in readiness for the execution of the character of the next impulse applied to the line circuit. Similarly, on the second deenergization of the line circuit, the step-by-step mechanisms at the control office and at the field stations take the second 10 step (with exceptions hereinafter noted).

For convenience in describing the present invention, each deenergization of the line circuit 15 will be referred to as an "off" period and each energization of the line circuit will be referred to as an "on" period. In this way the various relay operations of the system may be designated as occurring either during the initiating "on" and "off" 20 periods or during a particular "off" or "on" period of each step, in each case the reference being made to the condition of the line circuit.

The description of the operation of the system 25 is also facilitated by considering that each step is divided into a conditioning period and an executing period. The conditioning period is the first part of the step, that is, the "off" period during which the various relays are being conditioned 30 in readiness for the transmission of the next message. The stepping relay corresponding to the particular step is picked up during the "off" period. The executing period of each step is the second part of that step, that is, the "on" period, during which the character of the impulse applied 35 to the line circuit is effective to position the message storing relay which is to be controlled on that particular step. The VP relay associated with the stepping relay bank in the control office is shifted during each "on" period, being picked up during the initiating and even "on" periods 40 and dropped during odd "on" periods. The VP relay at the station is shifted during each "on" period (after the initiating period). It is picked up during each odd "on" period and dropped during each even "on" period.

Normal at-rest condition.—With the system in its normal or period of blank condition, the line circuit is normally energized with (—) potential on line conductor 12 for positioning the line 50 relays in the control office and at the various field stations to their left hand full line positions. Referring to Fig. 1, this circuit extends from the (+) terminal of battery OB, contact 21 of relay PC in its left hand position, back contact 24 of relay OBS, line conductor 10, back contact 27 of relay PC¹ at the intermediate field station, conductor 20, back contact 30 of relay PC⁴ at the end field station, back contacts 32 and 34 of relay FBS⁴, back contact 36 of relay PC⁴, winding of 55 relay F⁴, back contact 40 of relay P⁴, conductor 22, back contact 41 of relay PC¹, winding of relay F¹, back contact 45 of relay P¹, conductor 12, normally closed front contact 47 of relay EP, winding of relay F, back contact 50 of relay OBS 60 and contact 53 of relay PC in its left hand position, to the (—) terminal of battery OB. This circuit may also be traced on Figs. 2B and 3A, with the exception of certain contacts and relay windings not included, due to the fact that the 65 complete line circuit through the intermediate and end field stations is not shown in these two figures.

Relay PC (Fig. 2B) is energized with current flowing in the proper direction for positioning 70

75

its contacts to the left as shown, over a circuit which extends from (CN), winding of relay PC, conductor 90, back contacts 89, 88, 87, 86, and 85 of relays 5V, 4V, 3V, 2V, and 1V respectively, 5 conductor 84, back contact 83 of relay SR², back contact 81 of relay SR¹, conductor 80, front contact 79 of relay LOP and front contact 77 of relay LO, to (B-).

Relay EP is energized by means of a circuit extending from (+), back contacts 23 and 25 in multiple of relays OBS and 1FP respectively, upper winding of relay EP and front contact 26 of relay E, to (-). Relay LO is normally energized by means of a circuit extending from (+), contact 15 55 of relay F in its left hand position, back contact 51 of relay SA and upper winding of relay LO, to (-). Relay LOP is normally energized by means of a circuit extending from (+), back contact 66 of relay SAP, front contact 69 of relay 20 LO and winding of relay LOP, to (-). Relay E is normally energized by means of a circuit extending from (+), back contacts 91, 92, 93, 94, and 95 of stepping relays 5V, 4V, 3V, 2V, and 1V respectively, lower winding of relay E and back 25 contact 99 of relay VP, to (-).

At the field station, relay LO¹ is normally energized by means of a circuit extending from (+), contact 170 of relay F¹ in its left hand position, back contact 172 of relay SA¹ and lower 30 winding of relay LO¹, to (-). Relay LOP¹ is normally energized by means of a circuit extending from (+), contact 170 of relay F¹ in its left hand position, back contact 172 of relay SA, front contacts 179 and 174 of relay LO¹, and 35 winding of relay LOP¹, to (-). Relay CH¹ is normally energized by means of a circuit extending from (+), contacts 150, 151, 152, 153, 154, 155, and 156 of relays 2BT¹, 2AT¹, 1AB¹, 2M¹, 1M¹, WP¹, and TR¹ respectively in either their 40 front or back point positions, front contact 158 and upper winding of relay CH¹, to (-). These six relays are assumed to be normally energized by means of circuits which are not shown, since they are familiar to those skilled in the art and 45 since the detailed circuit arrangements for operating these relays are immaterial for the understanding of the present invention.

It will be assumed that the operator in the control office desires to move the track switch TS¹ 50 at the station indicated in Fig. 3B from a normally locked position to a reverse locked position. The normally locked position of the track switch is typified by the contacts of relay WP¹ being in the full line positions shown. After a discussion of the circuit operations effective to select the station and thereafter actuate the switch machine, resulting in a change in the position of the polar contacts of relay WP¹, an explanation of the operation of the system relating to the 55 transmission of indications back to the control office due to such a change in condition will be given.

Manual start.—With the system in its normal condition, the actuation of starting button SB 60 is effective to pick up the corresponding storing relay SR¹, followed by the picking up of the corresponding code determining relay CD¹. This initiates the system into a cycle of operations and determines the code which is to be transmitted 65 over the line circuit for the selection of the particular field station associated with button SB and levers SML and SGL. It will be understood that the storing relays can be picked up at any time the corresponding starting buttons are actuated, but only one code determining relay may 70

be energized at one time and only while the system is in its normal condition. The particular code determining relay which will be picked up at the start of an operating cycle, when several stations are to be selected, is determined by the 5 interconnection of these code determining relays as disclosed in the prior application of N. D. Preston et al., Ser. No. 455,304, filed May 24, 1930.

The picking up of relay SR¹ momentarily opens the above described energizing circuit for relay 10 PC and immediately establishes another energizing circuit for this relay of reversed polarity. The energizing circuit for relay PC now extends from (B+), front contact 81 of relay SR¹, back contact 83 of relay SR² and over the remainder 15 of the above described circuit to the winding of relay PC. Relay PC quickly shifts its contacts 21 and 53 to their right hand dotted positions, which is effective to momentarily deenergize the line and thereafter again energizing it with (+) potential applied to conductor 12 and (-) potential applied to conductor 10. This circuit extends from the (+) terminal of battery OB, contact 21 of relay PC in its right hand dotted position, back contact 50 of relay OBS, winding of relay 20 F, front contact 47 of relay EP, line conductor 12 and through the above described circuits at the field stations, line conductor 10, back contact 24 of relay OBS and contact 53 of relay PC in its right hand dotted position to the (-) 25 terminal of battery OB.

This reversal of current in the line circuit marks the end of the normal period and the beginning of the initiating period. The line relays in the control office and at the field station are 30 now actuated to their right hand dotted positions. A circuit is closed for picking up relay 1FP which extends from (+), contact 55 of relay F in its right hand dotted position and winding of relay 1FP, to (-). A circuit is closed for 35 picking up relay 2FP which extends from (+), front contact 17 of relay 1FP and winding of relay 2FP, to (-). Relay SA is picked up by means of a circuit extending from (+), front contact 43 of relay 2FP and winding of relay 40 SA, to (-). Relay SAP is picked up by means of a circuit extending from (+), front contact 18 of relay SA and winding of relay SAP, to (-).

The actuation of contact 55 of relay F from its 45 left hand position opens the normal energizing circuit through the upper winding of relay LO, but this relay is not released due to the fact that relay F closes a stick circuit for relay LO extending from (+), contact 67 of relay F in its right 50 hand dotted position, back contact 28 of relay SA, front contact 42 and upper winding of relay LO, to (-). As soon as relay SA is picked up, another stick circuit is closed for relay LO which is effective throughout the cycle and which extends from (+), front contact 18 of relay SA, 55 front contact 39 and lower winding of relay LO, to (-). Relay LO is slightly slow releasing due to the short circuit around its lower winding which extends from (-), back contact 18 of relay SA, front contact 39 of relay LO and lower winding of relay LO, to (-). To obviate any chance of relay LO dropping its armature when this short circuit is removed at the time relay SA picks up and opens its back contact 18, the arrangement and adjustment of back contact 28 may be such 60 that it is not opened until after front contact 18 is closed.

During the initiating period, a circuit is closed 65 for picking up relay VP which is effective as soon as relay SAP has been picked up and which 70

extends from (B+), front contact 29 of relay SAP, back contacts 71, 72, 73, 74 and 75 of the five stepping relays in series, upper winding of relay VP and front contact 44 of relay 2FP, to (CN). Relay VP closes a stick circuit for itself extending from (+), front contact 66 of relay SAP, front contact 48 and lower winding of relay VP, to (-). It will be noted that the current flow through both windings of relay VP at this time 10 is in the same direction.

The actuation of the VP relay contacts opens the above described energizing circuit of relay E at back contact 99, allowing relay E to drop, which in turn causes the dropping of relay EP by 15 opening the above described energizing circuit of this relay at front contact 26 of relay E. This marks the end of the initiating period and the beginning of the first "off" period, by deenergizing the line circuit at front contacts 37 and 47 of 20 relays E and EP respectively.

Relay LOP is deenergized and drops its contacts when relay SAP is picked up, due to this latter relay opening the above described energizing circuit of relay LOP at back contact 66 of 25 relay SAP. Relay LOP remains down until the change to normal period at the end of the cycle when it is again picked up as will be later described. Relays EPT and OBS remain down throughout this cycle.

30 While all this has been taking place at the control office, the field station circuits have likewise been functioning to prepare for the cycle of operations which follows. Although the description will be specifically directed to the field 35 station illustrated in Figs. 3A and 3B, it will be understood that similar operations take place at the other stations along the line (with exceptions later pointed out).

When relay F¹ is actuated to its right hand 40 dotted position in synchronism with relay F in the control office, a circuit is closed for picking up relay FP¹ which extends from (+), contact 170 of relay F¹ in its right hand dotted position and winding of relay FP¹, to (-). Relay FP¹ closes 45 a circuit for picking up relay SA¹ which extends from (+), front contact 176 of relay FP¹ and winding of relay SA¹, to (-). When relay F¹ actuates its contact 170 away from the left hand position, it interrupts the above described energizing circuit through the lower winding of relay LO¹, but establishes a stick circuit for this latter relay before it has time to release which 50 extends from (+), contact 171 of relay F¹ in its right hand dotted position, back contact 173 of relay SA¹, front contact 179 and lower winding of relay LO¹, to (-). This circuit continues 55 through front contact 174 of relay LO¹ and the winding of relay LOP¹, to (-) for maintaining this latter relay energized at this time.

60 When relay SA¹ picks up and opens its back contact 173 included in the above described circuit, relay LO¹ is not dropped because a substitute stick circuit is established extending from (+), front contact 182 of relay SA¹, conductor 183, 65 back contact 185 of relay 3V¹, conductor 187, front contact 188 of relay SA¹, front contact 190 and upper winding of relay LO¹, to (-). It is obvious that the contacts of relay SA¹ may be so arranged and adjusted that this circuit is 70 established at front contact 182 before the above described stick circuit through back contact 173 of relay SA¹ is broken. Relay LOP¹ is deenergized and drops its contacts after a predetermined time interval, due to the interruption of

the above described energizing circuit for this relay at back contact 173 of relay SA¹.

Relay VP¹ is not picked up during the initiating period. Its pick-up circuit is first established during the first "on" period as will later be described.

Impulsing and stepping operations.—It will be recalled that the system is advanced into the first "off" period when relay EP drops and deenergizes the line. This causes relay F to restore 10 its contacts to their deenergized positions, which opens the energizing circuit of relay 1FP at contact 55 of relay F. Relay 1FP drops and causes the release of relay 2FP by opening the energizing circuit of this latter relay at contact 17 of 15 relay 1FP. The release of relay 2FP opens the energizing circuit of relay SA at front contact 43, but relay SA (because of its slow releasing characteristics) is not dropped before relay 2FP is again picked up to reestablish this energizing 20 circuit. This same condition is effected during all of the impulse periods, so that it is unnecessary to repeat the explanation in connection with each impulse during the cycle.

The release of relay 2FP closes a circuit for 25 picking up stepping relay 1V which extends from (+), back contact 43 of relay 2FP, front contact 15 of relay SA, back contact 38 of relay EP, front contact 49 of relay VP, back contact 52 of relay 4V, back contact 54 of relay 2V and winding of relay 1V, to (-). Relay 1V establishes 30 a stick circuit for itself extending from (+), front contact 66 of relay SAP, front contacts 59 and winding of relay 1V, to (-).

Relay 1V interrupts the above described energizing circuit of relay PC at its back contact 85 but immediately reestablishes another energizing circuit for relay PC at front contact 85, which circuit is dependent for the selective positioning of relay PC upon the code jumper connections 35 as will be later explained. It will be assumed, however, that relay PC is actuated to one position or the other during each "off" period for connecting battery OB to the line circuit when impulsing relay E closes its front contact 37 for 40 energizing the line circuit.

Relay 1V establishes an energizing circuit for relay E which extends from (+), back contacts 91, 92, 93, and 94 of relays 5V, 4V, 3V, and 2V respectively, front contact 95 of relay 1V, upper winding of relay E and front contact 99 of relay VP, to (-). Relay E picks up and closes a circuit for picking up relay EP extending from (+), back contact 23 of relay OBS, upper winding of relay EP and front contact 26 of relay E, to (-). 55

The picking up of relay E closes the line circuit at its front contact 37, which extends through make-before-break back contact 47 of relay EP and over the remainder of the previously described circuit through contacts 21 and 53 of relay PC to battery OB. Relay EP in picking up maintains the continuity of the line circuit by closing front contact 47 before opening back contact 47.

This marks the end of the first "off" period and the beginning of the first "on" period by energizing the line circuit. Relay F actuates its contacts to either their right or left hand positions (as will be later explained), so that a circuit is closed for picking up relay 1FP which 60 extends from (+), contact 55 of relay F and winding of relay 1FP if contact 55 is positioned to the right, but if contact 55 is positioned to the left, the circuit extends through front con- 70

75

tact 57 of relay SA to the winding of relay 1FP. Relay 1FP again closes the above described energizing circuit for relay 2FP.

The picking up of relay 2FP closes a circuit which is effective to release relay VP, which circuit extends from (CN), front contact 44 of relay 2FP, upper winding of relay VP, back contacts 75, 74, 73, and 72 of relays 5V, 4V, 3V, and 2V respectively, front contact 71 of relay 1V and front contact 46 of relay VP, to (B-). Recalling that the lower winding of relay VP is energized by (+) potential applied to the right hand terminal of this winding and noting that (-) potential is now applied to the right hand terminal of the upper winding, it will be apparent that these two windings oppose with the result that the relay is restored to its deenergized position.

The dropping of relay VP opens the above described energizing circuit of relay E at front contact 99, so that relay E is dropped and by opening front contact 26, the energizing circuit of relay EP is interrupted and this latter relay is released.

25 This marks the end of the first "on" period and the beginning of the second "off" period by opening line conductor 12 at front contacts 37 and 47 of relays E and EP respectively. Relays F, 1FP, and 2FP are now deenergized as above described. Relay 2V is now picked up by means of a circuit extending from (+), back contact 43 of relay 2FP, front contact 15 of relay SA, back contact 38 of relay EP, back contact 49 of relay VP, back contact 51 of relay 5V, back contact 56 of relay 3V, front contact 58 of relay 1V and winding of relay 2V, to (-). Relay 2V establishes a stick circuit for itself, by way of its front contact 61, to (+) at front contact 66 of relay SAP. Relay E is again picked up by means of a circuit extending from (+), back contacts 91, 92 and 93 of relays 5V, 4V and 3V respectively, front contact 94 of relay 2V, lower winding of relay E and back contact 99 of relay VP, to (-). The picking up of relay E again closes the above described circuit for picking up relay EP and the above described circuit for energizing the line is again established, to mark the end of the second "off" period and the beginning of the second "on" period.

50 Relays F, 1FP, and 2FP are again picked up by means of the previously described circuits. Relay VP is picked up over a circuit extending from (CN), front contact 44 of relay 2FP, upper winding of relay VP, back contacts 75, 74, 55 and 73 of relays 5V, 4V, and 3V respectively and front contact 72 of relay 2V, to (B+). Relay VP establishes the above described stick circuit for itself by closing its front contact 48. The energizing circuit of the lower winding of relay E is now interrupted at back contact 99 of relay VP, so that relay E is dropped and the above described energizing circuit for relay EP is again interrupted to cause the release of this relay.

55 This marks the end of the second "on" period and the beginning of the third "off" period. Relays F, 1FP, and 2FP again release and a circuit is closed for picking up relay 3V which extends from (+), back contact 43 of relay 2FP, front contact 15 of relay SA, back contact 38 of relay EP, front contact 49 of relay VP, back contact 52 of relay 4V, front contact 54 of relay 2V and winding of relay 3V, to (-). Relay 3V establishes an obvious stick circuit for itself at its front contact 62. The energizing circuit 70 through the upper winding of relay E is now

established which extends from (+), back contacts 91 and 92 of relays 5V and 4V respectively, front contact 93 of relay 3V, upper winding of relay E and front contact 99 of relay VP, to (-). The actuation of relay E again closes the circuit 75 for picking up relay EP.

The line is again energized to mark the end of the third "off" period and the beginning of the third "on" period. Relays F, 1FP, and 2FP are again picked up and relay VP is dropped by establishing a circuit through its upper winding, which is in opposition to that in its lower winding and which extends from (CN), front contact 44 of relay 2FP, upper winding of relay VP, back contact 75 of relay 5V, back contact 74 of relay 4V, front contact 73 of relay 3V and front contact 46 of relay VP, to (B-). The energizing circuit through the upper winding of relay E is now interrupted at front contact 99 of relay VP so that relay E drops and in turn causes the 20 dropping of relay EP.

This marks the end of the third "on" period and the beginning of the fourth "off" period. Relays F, 1FP, and 2FP are now released and a circuit is closed for picking up relay 4V which 25 extends from (+), at back contact 43 of relay 2FP, over the remainder of the previously described circuit to contact 56 of relay 3V and since relay 3V is picked up, this circuit is extended through front contact 56 of relay 3V 30 and the winding of relay 4V, to (-). Relay 4V establishes an obvious stick circuit for itself by way of its front contact 63. Relay E is now picked up by means of a circuit which extends from (+), back contact 91 of relay 5V, front contact 92 of relay 4V, lower winding of relay E and back contact 99 of relay VP, to (-). Relay EP is again picked up as above described and the line is energized.

35 This marks the end of the fourth "off" period and the beginning of the fourth "on" period. Relays F, 1FP, and 2FP are now picked up in rotation and a circuit is established for picking up relay VP which extends from (CN), front contact 44 of relay 2FP, upper winding of relay VP, back contact 75 of relay 5V and front contact 74 of relay 4V, to (B+). Relay VP again establishes the above described stick circuit for itself and also opens the energizing circuit through the lower winding of relay E at back contact 99. 50 Relays E and EP are now released to deenergize the line.

40 This marks the end of the fourth "on" period and the beginning of the fifth "off" period. Relays F, 1FP, and 2FP are again dropped in turn, after which a circuit is established for picking up relay 5V, which circuit has been previously described up to contact 52 of relay 4V and which now extends through front contact 52 of relay 4V and the winding of relay 5V, to (-). Relay 5V establishes an obvious stick circuit for itself by way of its front contact 64. An energizing circuit is now established for relay E from (+), front contact 91 of relay 5V, upper winding of relay E and front contact 99 of relay VP, to (-), 60 which circuit is effective to pick up relay E, after which relay EP is picked up. The line is now energized as previously described.

45 This marks the end of the fifth "off" period and the beginning of the fifth "on" period. Relays F, 1FP and 2FP again pick up and the previously described circuit for effecting the release of relay VP is established, with the (-) potential applied to the right hand terminal of the upper winding of relay VP now completed through 75

front contact 75 of relay 5V. Relays E and EP are now released in turn, since the dropping of relay VP interrupts the above described energizing circuit through the upper winding of relay E at front contact 99 and the line deenergized.

This marks the end of the fifth "on" period and the beginning of the "change to normal" "off" period. Relays F, 1FP, and 2FP again release but this time there is no stepping relay to be picked up. This results in relays E and EP remaining down because there is no circuit for energizing relay E through its lower winding with relay VP down and relay 5V up. Since relays E and EP can not be picked up, the line is not again energized, so that relay 2FP remains down for a sufficiently long time interval to cause the release of relay SA by opening its energizing circuit at front contact 43 of relay 2FP. Relay SA interrupts the energizing circuit of relay SAP at its front contact 18, with the result that relay SAP is dropped after a predetermined interval of time.

The dropping of relay SA opens the stick circuit of relay LO at front contact 18 and after a short time interval, relay LO is dropped. All the stepping relays are dropped when relay SAP releases and opens their stick circuits at front contact 66. A circuit is now completed for picking up relay E extending from (+), through back contacts 91, 92, 93, 94 and 95 of the five stepping relays in series, lower winding of relay E and back contact 99 of relay VP, to (-). Relay EP is now picked up by means of the previously described circuit extending through its upper winding. The closure of front contacts 37 and 47 of relays E and EP respectively again energize the line circuit to mark the end of the "change to normal" "off" period and the beginning of the normal "on" period. If there are no other storing relays picked up, relay PC will actuate its contacts to their left hand positions by means of the previously described circuit which exists during the normal condition of the system. This effects the energization of the line circuit with a (-) potential applied to conductor 12 from battery OB, for positioning the line relay contacts to their left hand positions.

Since relay SA is down and relay F is in its left hand position, there is no circuit for energizing relay 1FP. Relay 1FP and relay 2FP remain down until the start of another cycle. Relay LO now has its original energizing circuit established by way of contact 55 of relay F in its left hand position. Relay LOP has its original energizing circuit established by way of back contact 66 of relay SAP and front contact 69 of relay LO. Relays LO and LOP are picked up.

It is not believed necessary to describe in detail the stepping relay operations at the field station, since these relays are picked up by means of circuits similar to the circuits of corresponding relays in the control office. It will be understood that relays F¹ and FP¹ operate substantially in synchronism with relays F and 2FP in the control office so that circuits similar to those above described are completed for picking up and sticking the five stepping relays of Fig. 3B.

The pick-up circuits for the odd stepping relays at the field station extend through back contact 269 of the half step relay VP¹ instead of through a front contact as is the case in the control office. Likewise, the even stepping relays at the field station are picked up through

a front contact (260) of the VP relay instead of a back contact (49) as in the case of the control office stepping relay operation. This is due to the fact that the half step relay at the field station is picked up first during the first "on" period after the first stepping relay has been picked up, so that it is necessary to extend the circuits to the odd stepping relays through a contact of the half step relay that is closed when this relay is down. The pick-up and operating circuits for relay VP¹ are similar to those described for relay VP. The pick-up circuits for the stepping relays at the field station are completed through either front contact 257 of relay LO¹ or front contact 256 of relay S¹. This results in the stepping relay operation being stopped at those stations which are not to be selected during a control cycle, as determined by both relays LO¹ and S¹ being down as will be later explained.

Stored office start conditions.—In the event that there are one or more storing relays up when the system advances into its "change to normal" period, it does not go into its normal condition but passes directly from the "change to normal" period of one cycle into the initiating period of the next cycle. This results in the line relays being positioned to the right as above explained in connection with the initiating period.

It will be assumed that relay SR² is up when the above described cycle reaches its "change to normal" period, due to a stored office start condition awaiting transmission. When the stepping relays drop, the previously described circuit through their back contacts 89, 88, 87, 86, and 85 to the winding of relay PC is not completed to (B-) by way of conductor 80, due to back contact 83 of relay SR² being open. The circuit of relay PC is completed to (B+) at front contact 83 of relay SR² so that relay PC is positioned to the right for energizing the line with (+) potential which actuates line relay F to the right.

Relays 1FP, 2FP, SA, and SAP now pick up. Relay LO does not pick up because its pick-up circuit through contact 55 of relay F in its left hand position is not closed before the circuit is opened at back contact 57 of relay SA. Relay LOP remains down because its pick-up and stick circuits are open at back contact 66 of relay SAP.

If at the end of this particular cycle, there are one or more storing relays up, the line is not energized with a normal (-) potential, but the next cycle starts off with a (+) potential applied to line 12 and relay LO remains down during this cycle for the same reason just discussed.

When the "change to normal" period of a cycle is reached, with no storing relay up, then (B-) through back contact 79 of relay LOP and back contacts of all storing relays in series is applied to the winding of relay PC over the previously described circuit. This positions relay PC to the left and restores the system to its normal condition by energizing line 12 with (-) potential which is effective to position the line relays to the left. The previously described circuits are now effective to pick up relays LO and LOP.

The circuit which normally energizes the lock-out relays at the stations (such as relay LO¹ of Fig. 3A) has been previously described. As will be later explained, only the lock-out relay associated with the station selected during a particular cycle remains up throughout that cycle.

This particular lock-out relay is dropped during the "change to normal" period because the energizing circuit of its upper winding is open at front contacts 182 and 188 of relay SA¹ and the energizing circuit of its lower winding is open at contacts 170 and 171 of relay F¹, now de-energized.

If the system is restored to its normal condition at the end of a cycle, all lock-out relays are 10 picked up during the normal period over circuits similar to that shown in Fig. 3A which extends from (+), contact 170 of relay F¹ in its left hand position, back contact 172 of relay SA¹ and lower winding of relay LO¹, to (-).

15 If the system starts another cycle without returning to normal, the line relays are not positioned to the left before the SA¹ relays are picked up. The lock-out relays are picked up during the initiating period over circuits similar to that 20 of Fig. 3A which extends from (+), back contact 182 of relay SA¹, front contact 181 of relay FP¹, back contact 180 of relay LOP¹, back contact 172 of relay SA¹ and lower winding of relay LO¹, to (-). Stick circuits of the lock-out 25 relays are established similar to that extending from (+), front contact 182 of relay SA¹, conductor 183, back contact 185 of relay 3V¹, conductor 187, front contact 188 of relay SA¹, front contact 190 and upper winding of relay LO¹, to 30 (-). Front contacts 182 and 188 of relay SA¹ are so organized that they make before back contacts 182 and 172 break.

Briefly, relay LO in the control office is up when the system is in its normal condition and 35 remains up during a cycle, irrespective of the station selected. It is dropped and again picked up during the "change to normal" period if there are no office start conditions waiting. It is not again picked up in the "change to normal" 40 period but remains down during the next cycle if there is an office start condition waiting. Relay LOP is up when the system is in its normal condition, is deenergized during the initiating period, remains down during the cycle until the 45 "change to normal" period, when it is picked up if there is no office start condition waiting, but remains down during the next cycle if there is an office start condition waiting.

At the field station, the lock-out relays and the 50 lock-out repeating relays are up when the system is in its normal at-rest condition. The lock-out repeating relays at all stations are dropped during the initiating period of a cycle, remain down throughout the cycle until the "change to normal" period, when they are picked up if there is no office start condition waiting. They are not picked up until a "change to normal" period is reached with no office start condition waiting.

60 The lock-out relays at those stations not selected during a cycle are dropped out during that cycle as will be later explained, only that lock-out relay associated with the selected station remaining up until the "change to normal" period, 65 when it is dropped. The lock-out relays at all stations are again picked up during the "change to normal" period if there are no office start conditions awaiting transmission, or if there is an office start condition waiting, these lock-out 70 relays are all picked up during the initiating period of the following cycle.

This operation of the lock-out and lock-out repeating relays will be later referred to in connection with the transmission of indications, be- 75 cause the reason for this particular operation is

to prevent a field station obtaining access to the communication circuit when it is being used to transmit controls and as long as there are stored controls waiting to be transmitted.

Transmission of controls.—It will be recalled 5 that the lock-out relays such as relay LO¹ of Fig. 3A at all field stations are up during the initiating period of each cycle. It will not be assumed that the station shown in Figs. 3A and 3B is to be selected and the switch machine at this 10 station moved from its normal locked position to its reverse locked position. The illustrated station is assumed selectable in response to a (-) and a (+) impulse applied to line 12 during the first two steps of the control cycle, as 15 determined by code jumpers 35 and 33 of Fig. 2A being connected to (B-) and (B+) respectively as shown. The connection of code jumper 210 of Fig. 3B from contact 211 of relay 2ST¹ in its right hand position to bus 187 determines that 20 this particular station responds to the code combination (--) (+).

It will be further assumed that the stepping relays in the control office and at the illustrated 25 field station operate in synchronism throughout the cycle as above explained. The impulse to be applied to the line circuit during the first "on" period is determined (-) during the preceding "off" period by relay PC of Fig. 2B being actuated to the left over a circuit extending from (CN), winding of relay PC, conductor 90, back contacts 89, 88, 87, and 86 of relays 5V, 4V, 3V, and 2V respectively, front contact 85 of relay 1V, conductor 101, front contact 31 of relay CD¹ and code jumper 35 in its full line position, to 30 (B-). When line 12 is energized during the 35 first "on" period, relays F and F¹ will be positioned to the left because the (-) terminal of battery OB is connected by way of contact 53 of relay PC in its left hand position, back contact 50 of relay OBS, winding of relay F and over the remainder of the two-wire line circuit previously described to the (+) terminal of battery OB.

Assuming that there are four field stations 45 connected to the line circuit, the four line relays such as relay F¹ of Fig. 3A are positioned to the left. Relay 1ST¹ (and similar relays at the other stations) is positioned to the left by means of a circuit extending from (CN), winding of 50 relay 1ST¹, conductor 201, front contact 291 of relay 1V¹, back contacts 292, 293, 294 and 295 of relays 2V¹, 3V¹, 4V¹, and 5V¹ respectively, conductor 290, front contact 281 of relay LO¹, front contact 280 of relay SA¹ and contact 296 55 of relay F¹ in its left hand position, to (B-).

Relay PC is positioned to the right during the second "off" period by means of a circuit which extends from (B+), code jumper 33 (Fig. 2A), front contact 65 of relay CD¹, conductor 102, 60 front contact 86 of relay 2V and over the remainder of the previously described circuit to the winding of relay PC. With relay PC actuated to the right, the line circuit is energized with a (+) potential because the (+) terminal of battery OB is now connected by way of contact 21 of relay PC in its right hand dotted position, back contact 50 of relay OBS and winding of relay F, to line conductor 12.

With the line relays at the stations positioned 70 to the right, a circuit is closed for positioning the station relays similar to relay 2ST¹ of Fig. 3B to the right by means of a circuit similar to that extending from (CN), winding of relay 2ST¹, conductor 202, front contact 292 of relay 75

$2V^1$ and over the remainder of the previously described circuit to contact 296 of relay F^1 now in its right hand dotted position, to (B+).

The station relays similar to relay $1ST^1$ at the 5 four stations will be positioned to the left and the station relays similar to relay $2ST^1$ at the four stations will be positioned to the right.

During the third "off" period, relay $3V^1$ is picked up to disconnect at its back contact 185 10 the energized stick conductor 183 from conductor 187. At all of the stations except that one with code jumper 210 connected as shown in Fig. 3B, this opening of back contact 185 deenergizes the stick circuit of the lock-out relays and they are 15 dropped. At the particular station illustrated, however, relay LO^1 is maintained energized throughout the remainder of the cycle by means of a circuit extending from (+), front contact 182 of relay SA^1 , conductor 183, contact 212 of 20 relay $1ST^1$ in its left hand dotted position, contact 211 of relay $2ST^1$ in its right hand position, code jumper 210, conductor 187, front contact 188 of relay SA^1 , front contact 190 and upper winding of relay LO^1 , to (-).

25 With four stations selectable with combinations of two impulses, it will be obvious that in addition to the station illustrated which responds to code combination (-) (+), the other three respond to combinations (+) (+), (+) (-) and (-) (-). For example, at the station where code jumper 213 is connected to conductor 187, the code combination is (+) (+) and the lock-out relay is maintained energized after the third step due to the circuit being completed from (+) 35 on stick conductor 183, by way of contacts 214 and 215 of relays $1ST^1$ and $2ST^1$ respectively in their right hand positions and code jumper 213 to conductor 187. At the station where code jumper 216 is connected to conductor 187, the 40 code combination for selecting this station is (+) (-), which requires that relays $1ST^1$ and $2ST^1$ be in their right and left hand positions respectively to complete the above described circuit for sticking the lock-out relay similar to 45 relay LO^1 . At the station where code jumper 217 is connected to conductor 187, the (-) (-) combination which positions the station relays similar to $1ST^1$ and $2ST^1$ to the left completes an energizing stick circuit for the lock-out relay.

50 After the station is selected, the switch machine SM^1 is controlled by the switch machine relay SMR^1 as determined by the position of the switch machine lever SML . To actuate the switch machine to its reverse locked position as 55 determined by relay SMR^1 actuating its contact 184 to the left, requires that the line circuit be energized with a (-) potential for positioning the line relays to the left. The switch machine lever SML in its left hand dotted position completes a circuit for actuating the contacts of relay 60 PC to the left which extends from (CN), winding of relay PC , conductor 99, back contacts 89 and 88 of relays $5V^1$ and $4V^1$ respectively, front contact 87 of relay $3V^1$, conductor 103, front contact 106 of relay CD^1 and contact 107 of the switch machine lever in its left hand dotted position, to (B-).

65 Relay PC positioned to the left energizes the line circuit with a (-) potential which positions relay F^1 to the left to actuate relay SMR^1 to the left over a circuit extending from (CN), winding of relay SMR^1 , conductor 203, front contact 293 of relay $3V^1$, back contacts 294 and 295 of relays $4V^1$ and $5V^1$ respectively, conductor 290, front contact 281 of relay LO^1 , front contact 280 of

relay SA^1 and contact 296 of relay F^1 in its left hand position, to (B-). Relay SMR^1 closes a circuit from (+), contact 184 in its left hand dotted position and the reverse winding of the switch machine motor SM^1 , to (-). It is obvious that the above conditions will be reversed with lever SML in its right hand position, with the result that the motor will be energized by way of contact 184 of relay SMR^1 in its right hand position to energize its normal operating winding.

70 It is believed that the above example is sufficient to indicate how other relays such as relays SG^1 and DR^1 at the field station are positioned as determined by the position of a lever such as SGL of Fig. 2A and that these relays may actuate signals in any approved manner by means of their contacts in different positions.

75 Relays such as SMR^1 , SG^1 and DR^1 at those field stations not selected during the cycle are not energized, because conductor similar to 290 at these other stations is open at contacts similar to 281 of the deenergized lock-out relays. After the third step at these other stations, which results in the dropping of the lock-out relays, the stepping operation is discontinued because the pick-up circuit of the stepping relays including conductors similar to 259 is open at front contacts similar to 257 of the lock-out relays at 80 these other stations.

85 *Automatic start.*—When a change in condition occurs at a field station, change relay CH^1 is dropped. This may be due to the entrance of a train into a detector track section, which deenergizes relay T^1 for in turn closing a circuit from (+), back contact 162 of relay T^1 and winding of relay TR^1 , to (-). Relay TR^1 picks up and closes a stick circuit for itself extending from (+), back contact 163 of relay $5V^1$ and back contact 165 of relay S^1 , front contact 164 and winding of relay TR^1 , to (-). It is obvious that the stick circuit remains effective until relay $5V^1$ is picked up at the end of the cycle with its associated S relay also picked up. This latter relay will be picked up at the station which obtains access to the communication line. Another relay similar to relay TR^1 at some other station is stuck up to store the change in condition, until the particular station with which this relay is associated obtains access to the communication circuit and relays similar to S^1 and $5V^1$ are up at such station.

90 A change in condition at the field station may be brought about as a result of relay WP^1 being momentarily deenergized as the switch machine is moved from its normal locked position to its reverse locked position, as a result of the control cycle previously discussed. In any event, the stick circuit of relay CH^1 is interrupted at some contact, such as 155 of relay WP^1 allowing relay CH^1 to drop and close a circuit for picking up relay CHP^1 extending from (+), back contact 182 of relay SA^1 , back contact 181 of relay FP^1 , front contact 160 of relay LO^1 , winding of relay CHP^1 , conductor 159 and back contact 157 of relay CH^1 , to (-). Relay CHP^1 closes a circuit for picking up relay P^1 which extends from (+), front contact 161 of relay CHP^1 and winding of relay P^1 , to (-).

95 This marks the end of the normal period (line relays in their left hand position) and the beginning of the initiating period, by deenergizing the line circuit at back contact 45 of relay P^1 . Relay F in the control office, relay F^1 at the illustrated field station and other line relays at the 100

other stations are dropped to their neutral positions. Relay LO in the control office is now dropped because its energizing circuits are opened at contacts 67 and 55 of relay F in its neutral position. Relay LO is not picked up during this cycle because relay SA opens its back contact 57 before relay F is again actuated to the left to close its contact 55.

Relay LO¹ at the illustrated field station (as well as the other lock-out relays at all other stations) is now dropped because its energizing circuit is open at contacts 170 and 171 of relay F¹ in their neutral positions. The lock-out relays at all stations remain down during this cycle.

Conductor 186 leading to the upper winding of relay FBS⁴ and contacts 192 and 193 of relays LOP¹ and LO¹ respectively are only used at the end field station, but in order to indicate how relay FBS⁴ at the end field station is picked up at the start of an indication cycle, this conductor and these contacts have been shown in association with Fig. 3A. It will be understood that contacts similar to 192 and 193 are on corresponding relays at the end field station only. Relay FBS⁴ is picked up by means of a circuit similar to that extending from (+), back contact 194 of relay SA¹, back contact 193 of relay LO¹, front contact 192 of relay LOP¹ and upper winding of relay FBS⁴, to (-).

Since relay P¹ is up, conductor 12 extending from this field station toward the control office is open, but a circuit is effective to energize the line at this calling field station in series with any other station or stations toward the end of the line, as well as the end station. This circuit extends from the (+) terminal of battery FB⁴ (see Fig. 1), front contact 32 of relay FBS⁴, back contact 30 of relay PC⁴, conductor 29, back contact 27 of relay PC¹, resistance R¹, front contact 195 of relay CHP¹, upper winding of relay S¹, front contact 45 of relay P¹, winding of relay F¹, back contact 41 of relay PC¹, conductor 22, back contact 40 of relay P⁴, winding of relay F⁴, back contact 36 of relay PC⁴ and front contact 34 of relay FBS⁴ to the (-) terminal of battery FB⁴.

The current flow in this circuit is of such a direction that relay F¹, and other similar line relays farther out the line, are positioned to the right and relay S¹ at this particular calling station is picked up. The dropping of relay LO¹ above described, opens the circuit of relay CHP¹ at front contact 160, but before relay CHP¹ has time to drop, a substitute circuit is closed which extends from (+), contact 171 of relay F¹ in its right hand dotted position, back contact 173 of relay SA¹, back contact 179 of relay LO¹, front contact 177 of relay CHP¹, back contact 160 of relay LO¹, winding of relay CHP¹, conductor 159 and back contact 157 of relay CH¹, to (-).

Relay F¹ closes a circuit for picking up relay FP¹ which extends from (+), contact 178 of relay F¹ in its right hand dotted position and winding of relay FP¹, to (-). Relay FP¹ closes a circuit for picking up relay SA¹ which extends from (+), front contact 176 of relay FP¹ and winding of relay SA¹, to (-). Relay SA¹ opens the above described energizing circuit for relay CHP¹ at back contact 173 causing the release of relay CHP¹. Even though relay CH¹ is dropped as a result of another start condition, relay CHP¹ cannot be picked up until the system goes into the normal condition because of the open circuit at front contact 160 of relay LO¹.

This also applies to other field stations, that is, a change resulting in the dropping of a relay

similar to relay CH¹ cannot pick up the change repeating relay similar to relay CHP¹ because the lock-out relays at all these other stations are down. Because of this condition, the system will function to transmit all the waiting controls in the control office before a relay such as relay CHP¹ can be picked up. This is because as long as there are stored controls to be transmitted the system does not go into its normal condition for picking up the lock-out relays, this being discussed in detail in connection with stored office start conditions.

The picking up of relay SA¹ reenergizes relay CH¹ over a circuit extending from (+), front contact 182 of relay SA¹, conductor 183, back contact 268 of relay IV¹, conductor 175, front contact 166 of relay CHP¹, front contact 167 of relay S¹, conductor 168 and lower winding of relay CH¹, to (-). Relay CH¹ of course will be stuck up until some change in condition takes place to interrupt the stick circuit through its upper winding.

The picking up of relay SA¹ also opens the circuit of relay LOP¹ (including its front contact 169) at back contact 194 of relay SA¹, which causes the release of relay LOP¹ and it remains down throughout the remainder of this cycle. The picking up of the relay similar to relay SA¹ at the end field station closes a circuit for sticking relay FBS⁴, which is similar to that extending from front contact 194 of relay SA¹, conductor 178, front contact 196 and lower winding of relay FBS⁴, to (-). It will be noted that contact 194 is of the make-before-break type so that this stick circuit is closed before the pick-up circuit through the upper winding of relay FBS⁴ is interrupted. Relay SA¹ closes a stick circuit for relay S¹ extending from (+), front contact 194 of relay SA¹, front contact 197 and lower winding of relay S¹, to (-). Since these stick circuits are maintained throughout this cycle, relays S¹ and FBS⁴ remain up during the cycle.

During the initiating period, relays PC in the control office is normally positioned to the left over the previously described circuit which extends from the winding of relay PC, to (B-), through front contacts 77 and 79 of relays LO and LOP respectively. When relay LO is dropped during the initiating period, the potential is shifted from (B-) to (B+) at back contact 71 of relay LO which positions relay PC to the right. When relay SAP is picked up during the initiating period (as will be later explained), relay LOP is dropped because its energizing circuit is opened at back contact 66 of relay SAP. (B-) potential is then applied through back contact 79 of relay LOP to the winding of relay PC so that this latter relay is positioned to the left in preparation for the next control cycle. The positioning of contacts 21 and 53 to the left after the release of relay LOP is ineffective, because relay OBS will be picked up to interrupt the circuit from battery OB through back contacts 24 and 50 as will be later described.

Referring to the field station circuits, the dropping of relay CHP¹ previously explained opens the circuit of relay P¹ at front contact 161, which results in the release of relay P¹. The line circuit from the calling station back to the control office is now energized by batteries OB and FB⁴ in series. This energizing circuit may be traced from the (+) terminal of battery FB⁴ (see Fig. 1), front contact 32 of relay FBS⁴, back contact 30 of relay PC⁴, conductor 20, back

contact 21 of relay PC¹, conductor 10, back contact 24 of relay OBS, contact 53 of relay PC in its right hand dotted position (this happens before relay LOP is dropped to shift relay PC to the left), (−) terminal of battery OB, (+) terminal of battery OB, contact 21 of relay PC in its right hand dotted position, back contact 50 of relay OBS, winding of relay F, front contact 47 of relay EP, conductor 12, back contact 45 of relay P¹, winding of relay F¹, back contact 41 of relay PC¹, conductor 22, back contact 40 of relay P⁴, winding of relay F⁴, back contact 36 of relay PC⁴ and front contact 34 of relay FBS⁴, to the (−) terminal of battery FB⁴. It will be understood that this circuit also includes the line relays at all other stations.

Line relay F (and similar relays farther out the line) remain in their right hand positions and the other line relays (in the line towards the control office) including relay F in the control office, are actuated to their right hand positions. The previously described circuit is now closed for picking up relay EP. Relays 2FP, SA, and SAP now pick up as described in connection with the initiating period of the control cycle, after which relay VP picks up and causes the release of relays E and EP in turn, all of which has been described in connection with the initiating period of the control cycle.

The dropping of relays E and EP deenergizes the line by opening front contacts 37 and 47. Relay OBS is now picked up by means of a circuit extending from (+), front contact 68 of relay SA, winding of relay OBS, back contact 78 of relay EP, front contact 76 of relay LOP and back contact 70 of relay LO, to (−). Relay OBS completes a stick circuit for itself which is effective during the remainder of this cycle and which extends from (+), front contact 68 of relay SA, winding and front contact 82 of relay OBS, to (−).

The system now steps through the cycle and the line is impelled by means of relays E and EP in the same manner previously described in connection with the control cycle with the following exceptions:—Relay LO in the control office is down and relay OBS is up. Relay EPT is conditioned to record indication code combinations as will be later explained. The lock-out relays at all stations are down and relay S¹ at the calling station only is up. Relay FBS⁴ at the end station is up and relays P¹ and PC¹ at the calling station are conditioned as determined by the indication code to be transmitted. The length of each “on” period is variable in a manner to be later explained.

Registration of the field station.—With jumpers 198 and 199 in the positions shown in Fig. 3B, the illustrated station will be registered in the control office during the first step of the indication cycle. It will be assumed that the system steps through the cycle in the previously described manner. With jumper 198 in the position shown, relay PC¹ is not picked up during the first “off” period, which results in the line circuit being energized with (+) potential during the following first “on” period. This is due to the fact that the above described circuit from battery FB⁴ is through back contacts 27 and 41 of relay PC¹ and is in the proper direction to position all the line relays to the right. It will be understood that battery OB is excluded from the above described circuit when relay OBS picks up and closes its front contacts 24 and 50 to complete the energizing circuit for the line from battery FB⁴ alone.

With relay F positioned to the right during the first “on” period, a circuit is closed for picking up the first pilot relay IPT which extends from (B+), contact 96 of relay F in its right hand dotted position, front contact 19 of relay SA, front contact 97 of relay OBS, back contacts 110, 111, 112 and 113 of relays 5V, 4V, 3V, and 2V respectively, front contact 114 of relay 1V, conductor 131 and upper winding of relay IPT, to (B−). Relay IPT closes a stick circuit for itself extending from (+), front contact 68 of relay SA, conductor 98, front contact 130 and lower winding of relay IPT, to (−).

In the event that a particular station is transmitting which has its jumper 198 connected in its alternate position leading to (+), then relay PC¹ is picked up during the first “off” period over a circuit extending from (+), jumper 198, conductor 231, front contact 200 of relay 1V, back contacts 206, 207, 208 and 209 of relays 2V¹, 3V¹, 4V¹, and 5V¹ respectively, conductor 191, winding of relay PC¹ and front contact 218 of relay S¹, to (−). With relay PC¹ up, the connection of battery FB⁴ to line conductors 10 and 12 is reversed which is effective to actuate relay F to the left. This closes a circuit from (B−) at contact 96 of relay F in its left hand position to the upper winding of relay IPT and since the same potential is applied to both terminals of this winding, relay IPT remains down.

The above example illustrates the manner in which a choice of two polar indications are obtained during one step to condition a pilot relay by picking it up or leaving it down. Although these polar impulses are effective to position the line relays at all stations, they are not repeated at these stations because all lock-out relays are down and front contacts similar to 281 are open.

The system is also arranged to transmit an additional choice of two conditions during each step by means of long and short energized conditions of the line. More specifically, during each step of an indication cycle, the line circuit may be energized for a comparatively long interval due to the control office opening the line circuit to mark the end of the “on” period. The field station may open the line circuit before it would otherwise be opened in the control office, to mark the end of the “on” period in a comparatively shorter length of time than when this “on” period is terminated in the control office. These two conditions are determined at the field station in accordance with whether conductors 231 and 233 are deenergized during the “on” period for providing a normally long “on”, or energized during the “on” period to provide an abnormally short “on”.

When the system is advanced from the first “off” period into the first “on” period by relay E in the control office picking up to energize the line, a circuit is closed for picking up relay EPT which extends from (+), front contact 23 of relay OBS, winding of relay EPT and front contact 109 of relay E, to (−). The line relays and the line repeating relays in the control office and at the field station are picked up during this “on” period in the manner previously described. Relay VP¹ is picked up and relay VP is dropped during the first “on” period as previously explained. When relay VP¹ picks up, (+) is applied to conductor 237 at front contact 239 of relay VP¹ and with jumper 199 in the position indicated in Fig. 3B, this is ineffective since the circuit is open at this point. This results in relay P¹ remaining down during this “on” period so that the line

circuit is not opened at the field station but remains closed until opened in the control office.

When relay VP in the control office drops, impulsing relay E is released as above described, 5 but relay EP does not drop at this time because of a stick circuit extending from (+), contact 55 of relay F in either its right or left hand position, front contact 14 of relay EPT, front contact 13 and lower winding of relay EP, to (-). 10 The dropping of relay E opens the circuit of relay EPT at front contact 109 and after a predetermined interval of time, relay EPT drops and opens the above described stick circuit for relay EP at contact 14. Relay EP now drops and the 15 line is deenergized to mark the end of the first "on" period.

Relays F, 1FP, and 2FP now drop in sequence and during the interval after relay 2PT drops and until relay 2FP is dropped, the executing 20 circuit for the long "on" is completed. This circuit extends from (B-), back contact 11 of relay EPT, front contact 9 of relay 2FP, front contact 8 of relay OBS, conductor 7, back contacts 115, 116, 117 and 118 of relays 5V, 4V, 3V, and 25 2V respectively, front contact 119 of relay 1V, conductor 121 and upper winding of relay 2PT, to (B-). Since both terminals of this winding of relay 2PT are connected to (B-), the relay remains down to register the fact that the calling 30 station is one where jumper 199 is not connected to conductor 237.

In the event that the calling field station is one with its jumper 199 connected to jumper 237, then when relay VP¹ picks up and closes its front 35 contact 239 as above described, the circuit is extended from (+) at this contact through jumper 199, conductor 221, front contact 230 of relay 1V¹, back contacts 229, 228, 227, and 226 of relays 2V¹, 3V¹, 4V¹, and 5V¹ respectively, conductor 298, front contact 219 of relay S¹, front contact 220 of relay FP¹ and winding of relay P¹, to (-). Therefore, relay P¹ picks up and opens the line circuit as soon as relay VP¹ shifts at the calling station.

45 Relay EPT in the control office is of course picked up at the start of the "on" period as before and when relay P¹ opens the line circuit, relays F, 1FP, and 2FP in the control office are dropped. Since the line is deenergized earlier 50 than during the alternate condition above described, relay F is dropped to its neutral position to close a circuit from (B+), contact 100 of relay F in its deenergized position, front contact 11 of relay EPT, front contact 9 of relay 2FP, 55 front contact 8 of relay OBS, conductor 7 and over the remainder of the above described circuit to the upper winding of relay 2PT. Relay 2PT is picked up this time because (B+) is applied to the right hand terminal of its upper winding and 60 it is stuck up over an obvious stick circuit including its front contact 120.

Relay EP is dropped as soon as relay F is restored to its neutral position to open its contact 55. It will be noted that the upper winding of relay EP is deenergized at this time because relays OBS and 1FP are picked up. As soon as the half step relay VP is shifted, relay E is dropped to maintain the circuit of the upper winding of relay EP open until the start of the next "on" 70 period. Relay EPT does not drop during this condition after relay E drops and opens its front contact 109, because of a stick circuit extending from (-), back contact 126 of relay EP, front contact 127 of relay EPT, winding of relay EPT 75 and front contact 23 of relay OBS, to (+).

The above example indicates how a station sends a message to the control office which records the fact whether or not this station has its code jumper 199 in connection with bus wire 237, by picking up pilot relay 2PT if this jumper is so connected and leaving pilot relay 2PT down if the jumper is not so connected. 5

The above two examples indicate how a choice of four indications is obtained during a single step for registering calling stations in the control office. With jumpers 198 and 199 in the positions shown in Fig. 3B, relay 1PT is up and relay 2PT is down when the system is advanced into the second "off" period, which occurs after the station registration code has been transmitted. A 15 circuit is now closed for picking up station relay ST which extends from (+), front contact 23 of relay OBS, conductor 6, front contact 128 of relay 2V, conductor 129, back contact 139 of relay 2PT, front contact 138 of relay 1PT and winding of relay ST, to (-). Relay ST remains energized until the end of the cycle. 20

Since the pilot relays 1PT and 2PT can be positioned in any one of four combinations during one step of the cycle by the four different possible combination connections of jumpers 198 and 199, any one of four field stations may register itself in the control office during one step. The four different combinations of the two jumpers are; first, 198 connected to (+) and 199 connected to conductor 237 resulting in relay 1PT remaining down and relay 2PT being picked up; second, with jumper 198 connected to (+) and jumper 199 disconnected from wire 237, relay 1PT remains down and relay 2PT remains down; third, jumper 198 disconnected from (+) and jumper 199 connected to wire 237 results in relay 1PT being picked up and relay 2PT being picked up; fourth, jumper 198 disconnected from (+) and jumper 199 disconnected from wire 237, relay 1PT is 30 35 40 picked up and relay 2PT remains down.

With these four pilot relay combinations, four station relays such as relay ST can be selectively picked up to register any one of four calling stations. With two additional pilot relays operated 45 in the same manner during the second step, sixteen station relays similar to relay ST can be selectively picked up to register any one of sixteen calling stations in the control office.

Indications from registered station.—After the 50 calling station registers itself in the control office, the particular indications from this station are transmitted during additional steps of the system. When the station is registered during the first step, the first indication condition from the station is executed during the second "on" period. 55

Assuming that relay WP¹ of Fig. 3B actuated its polar contact 240 to its left hand dotted position as a result of the previously described control cycle, this position of contact 240 indicates 60 that the switch machine has been moved to its reverse locked position. It will also be assumed that the detector track section illustrated is occupied and as a result, relay TR¹ is picked up.

When the system advances into the second "off" 65 period, relays F¹ and FP¹ at the transmitting field station will be dropped and relay 2V¹ will be picked up. A circuit is now closed for picking up relay PC¹ which extends from (+), front contact 241 of relay WP¹, contact 240 of relay WP¹, 70 in its left hand dotted position, conductor 232, front contact 206 of relay 2V¹ and over the remainder of the previously described circuit through the winding of relay PC¹, to (-) at front contact 218 of relay S¹. The picking up of re- 75

lay PC¹ connects battery FB⁴ to the line circuit in such a direction that the line relays will be positioned to the left when the line is energized to start the second "on" period, since current 5 from the (+) terminal of battery FB⁴ now extends through front contact 32 of relay FBS⁴, front contact 27 of relay PC¹ and over the lower line conductor 12, returning by way of the upper line conductor 10 to the (-) terminal of battery 10 FB⁴ through front contact 41 of relay PC¹ and front contact 34 of relay FBS⁴.

Relay F in the control office in its left hand position closes a circuit for actuating the No. 1 indication receiving relay 1IR to its right hand 15 position, which circuit extends from (B-), contact 96 of relay F in its left hand position, front contact 19 of relay SA, front contact 97 of relay OBS, back contacts 110, 111, and 112 of relays 5V, 4V and 3V respectively, front contact 113 of 20 relay 2V, conductor 32, front contact 136 of relay ST and winding of relay 1IR, to (CN).

When the system advances into the third "off" period, the picking up of relay 3V¹ extends the circuit from relay PC¹, by way of front contact 25 207 of relay 3V¹ and conductor 232 to polar contact 240 of relay WP¹ in its right hand position. Since it was assumed that relay WP¹ has its contact 240 actuated to the left hand dotted position, the energizing circuit for relay PC¹ is incomplete 30 during the third "on" period, so that the line is energized through back contacts 27 and 41 of relay PC¹ to position the line relays to the right.

Relay F closes a circuit from (B+), at contact 96 in its right hand dotted position through front 35 contact 19 of relay SA, front contact 97 of relay OBS, back contacts 110 and 111 of relays 5V and 4V respectively, front contact 112 of relay 3V, conductor 133, front contact 137 of relay ST and winding of relay 2IR, to (CN). This circuit is effective to position relay 2IR to the left.

With relay 1IR positioned to the right and relay 2IR positioned to the left, as a result of relay WP¹ being positioned to the left to indicate a reverse locked condition of the switch machine, a 45 circuit is completed for lighting lamp R to indicate this condition. This circuit extends from (+), contact 141 of relay 1IR in its right hand position, contact 142 of relay 2IR in its left hand position and lamp R, to (-).

In the event that polar contact 240 of relay 50 WP¹ is in its right hand position due to the switch machine being normally locked, then the above described circuit during the second "off" period is ineffective to pick up relay PC¹. This 55 results in the line circuit being energized with current in the opposite direction to that above explained, so that relay F actuates its contact 96 to the right and relay 1IR is positioned to the left, because (B+) from contact 96 in its right hand dotted position is connected to the winding of relay 1IR over the above described circuit.

The alternate condition of relay WP¹ at the third step, that is contact 240 in its right hand position, is effective to pick up relay PC¹ which 60 positions relay F to the left for closing the above described circuit from (B-) at contact 96 of relay F to the winding of relay 2IR, which in turn positions relay 2IR to the right.

Relay 1IR positioned to the left and relay 2IR 70 positioned to the right closes a circuit from (+), contact 142 in its right hand position and contact 141 in its left hand position, to lamp N, which lights this lamp as an indication that the switch machine is in the normal locked position.

75 In the event that contact 241 of relay WP¹ is in

its deenergized position, then there is no energizing circuit for relay PC¹ on either the second or third steps so that the line conductor is energized in such a direction that relay F in the control office is positioned to the right on both 5 the first and second steps. (B+) at contact 96 in its right hand dotted position is then connected to both indication receiving relays 1IR and 2IR in turn, to position both of these relays to the left. This results in both lamps N and R remaining relatively dark as an indication that the switch machine is in its unlocked or mid-stroke position.

As typical of the manner in which the short and long "on" periods may be used to transmit indications, it will be assumed that relay TR¹ is picked up. When relay VP¹ drops during the second "on" period, a circuit is closed for picking up relay P¹ which extends from (+), back contact 239 of relay VP¹, conductor 238, front contact 236 of relay TR¹, conductor 222, front contact 229 of relay 2V¹ and over the remainder of the previously described circuit to the winding of relay P¹. Relay P¹ picks up and deenergizes the line circuit at its back contact 45. This 25 marks the end of the second "on" period, this energized period of the line being comparatively short due to the field station opening the line circuit before relays E and EP in the control office drop to open the line.

Relays F, 1FP, and 2FP now drop. Since relay VP is picked up during the second "on" period, relays E and EP are dropped. Relay EPT (picked up when relay E was picked up to close its front contact 109) is now stuck up even 35 though front contact 109 is opened, by means of a circuit to (-) through front contact 127 of relay EPT and back contact 126 of relay EP.

Relay F in its neutral position closes a circuit from (B+), contact 100, front contact 11 of relay EPT, front contact 9 of relay 2FP, front contact 8 of relay OBS, conductor 1, back contacts 115, 116 and 117 of relays 5V, 4V, and 3V respectively, front contact 118 of relay 2V, conductor 122, front contact 143 of relay ST and winding of relay 3IR, to (CN). This actuates contact 146 of relay 3IR to the left hand dotted position, which lights lamp OS as an indication that the detector track section of Fig. 3B is occupied.

In the event that relay TR¹ is down, then the above described circuit for picking up relay P¹ is not completed, which results in the line remaining energized for a comparatively long interval until it is opened in the control office. Under this condition, relay E is dropped during the second "on" period when relay VP picks up as previously described. Relay EP is not dropped under this condition until after relay EPT drops because of the stick circuit extending from (+), contact 55 of relay F in either its right or left hand position, front contact 14 of relay EPT, front contact 13 and lower winding of relay EP, to (-).

When relay EPT drops, the above described 65 stick circuit of relay EP is opened allowing this latter relay to be deenergized to mark the end of the second "on" period by opening the line circuit. Relays F, 1FP, and 2FP now drop in sequence and during the interval after the dropping of relay EPT and until the dropping of relay 2FP, a circuit is closed from (B-), back contact 11 of relay EPT, front contact 9 of relay 2FP, front contact 8 of relay OBS, conductor 1, back contacts 115, 116, and 117 of relays 5V, 4V 70 75

and 3V respectively, front contact 118 of relay 2V, conductor 122, front contact 143 of relay ST and winding of relay 3IR, to (CN). The current in this circuit is of such a direction that relay 15 3IR is positioned to the right which deenergizes lamp OS as an indication that the detector track section associated with this lamp is unoccupied.

It is believed that the above typical examples are sufficient to indicate how indications are 10 transmitted during an indication cycle on both a single choice of four per step and two choices of two each per step. The single choice of four has been explained in connection with the registration of one of four stations during the first step, while 15 one choice of two has been explained in connection with displaying the OS indication on the second step. Although a choice of three as determined by the three different conditions of relay WP¹ during two steps of a system has been explained, it will be understood that (+) potential or zero potential applied to conductor 232 at the second step is effective to position an indication receiving relay such as relay 1IR to the 20 right or to the left respectively, in the above described manner to obtain a choice of two per step. It is therefore not believed necessary to explain the details of transmitting indications relating to the positions of relays 1M¹, 2M¹, 1AT¹, 2AT¹, and 2BT¹, since these indications are transmitted 25 on following steps of the cycle in the same manner as already described in connection with the second step.

Lock-out.—In the description relating to the automatic start condition, it was explained how 35 a field station is prevented from obtaining access to the communication line after the system has been initiated into a cycle of operations, as long as there are controls to be transmitted. It will now be explained how the system functions to 40 first transmit indications and thereafter all stored controls when simultaneous field and office start conditions exist with the system in its normal condition. Thereafter an explanation will be given of the operation which is effective to give 45 only one station access to the line when two or more stations have indications to transmit at the same time, with no controls awaiting transmission.

It has previously been explained that the polarity of the current in the line circuit is quickly 50 changed from (−) to (+) during the initiating period of a control cycle. It has also been explained that, when the system is initiated into an indication cycle, the line which is normally 55 energized (−) is opened so that the control office cannot energize the line circuit, with the result that all the lock-out relays at the field stations are dropped and the relay such as relay S¹ at the calling station is picked up.

60 It is obvious that the opening of a series line circuit is a superior condition to reversing the current flow in the line circuit. This condition may be best understood by considering the schematic line circuit illustrated in Fig. 1 and 65 noting that the line circuit is normally energized with (−) potential applied to conductor 12. Should the control office endeavor to initiate the system into a control cycle by actuating the polar contacts of relay PC to their right hand dotted 70 positions simultaneously with the opening of back contact 45 of relay P¹, for example, the result is that the reverse current flow is ineffective but the open line condition is effective to initiate the system into an indication cycle. The next cycle, 75 however, functions to transmit controls irrespec-

tive of the existence of indication conditions waiting to be transmitted, in the manner which has previously been explained.

It may happen that two or more field stations have new indications to transmit at the same time while the system is in its normal condition. In this case it is necessary to permit only one of these stations to obtain access to the communication line in order to prevent mutilation of code combinations.

10 Referring to Fig. 1, it will be assumed that the intermediate field station and the end field station have new indications to transmit at the same time, when the system is in its normal condition. The release of the change relays at these two stations as a result of the new indications to be transmitted, is effective to pick up relays CHP¹ and CHP⁴ over circuits which are similar to that previously described in connection with Figs. 3A and 3B. The closure of the front contact similar to 15 161 (see Fig. 3A) of these change repeating relays is effective to pick up relays P¹ and P⁴. The normally energized line circuit is now opened at contacts 45 and 40 of relays P¹ and P⁴ respectively, which is effective to initiate the cycle of 20 operations in the previously described manner, by dropping the line relays and the lock-out relays in the control office and the field stations, after 25 which relay FBS⁴ is picked up.

A circuit is now established for energizing relay S⁴ which extends from the (+) terminal of battery FB⁴, front contact 32 of relay FBS⁴, back contact 30 of relay PC⁴, resistance R⁴, front contact 16 of relay CHP⁴, upper winding of relay S⁴, front contact 40 of relay P⁴, winding of relay F⁴, back contact 36 of relay PC⁴ and front contact 34 of relay FBS⁴, to the (−) terminal of battery FB⁴. Relay S⁴ establishes a stick circuit for itself which is similar to that extending from (+), front contact 194 of relay SA¹, front contact 197 and 30 lower winding of the relay similar to relay S¹, to (−).

35 It will be understood that the relays similar to relays FP¹ and SA¹ at the end field station are picked up when relay F⁴ picks up as a result of 40 the above described energizing circuit through the winding of relay F⁴.

45 At the intermediate field station, the operation of relay CHP¹ is ineffective to pick up relay S¹ because the continuity of the line circuit is broken at back contact 40 of relay P⁴. At the time the line was deenergized and the line relays were dropped to cause the release of the lock-out relays, the circuit of the change repeating relay at the intermediate field station was deenergized by the 50 contact similar to contact 160 of the relay similar to relay LO¹, breaking its front point. The back contact similar to 160 extends by way of a circuit 55 similar to that through front contact 171 of relay CHP¹ of Fig. 3A, back contact 179 of relay LO¹, back contact 173 of relay SA¹, to contact 171 of relay F¹ in its deenergized position, which circuit is deenergized, resulting in the release of the change repeating relay CHP¹ at the intermediate station.

60 At the end field station, the dropping of the lock-out relay closes a similar circuit but at this station, the contact similar to 171 of relay F⁴ is in its right hand dotted position, which connects (+) potential to the winding of relay CHP⁴ for 65 sticking this relay. This circuit is not shown in detail in Fig. 1 but it may be traced by considering the detailed circuit of Fig. 3A as being duplicated at the end field station. This results in the change repeating relay at the intermediate station 70

being dropped while the one at the end station is stuck up.

The dropping of the change repeating relay at the intermediate field station causes the release of relay P⁴ by opening front contact similar to 161 of Fig. 3A. At the end field station, relay CHP⁴ is deenergized when the relay similar to relay SA¹ picks up and opens its back contact 173. Relay P⁴ at the end station now deenergizes because the dropping of relay CHP⁴ opens its front contact similar to 161.

Since relays P¹ and P⁴ are now down, the continuity of the line circuit from the end station to the control office is reestablished and the line relays are picked up, by means of the current flowing from the field battery FB⁴ and the office battery OB as previously described. The system now advances through the cycle as above explained with relay S⁴ stuck up to (+) at the front contact similar to 194 of the relay similar to relay SA¹ at the end station. Relays CHP¹ and S¹ at the intermediate station remain down during this cycle and cannot be energized until the system returns to normal, when they have another chance to be picked up.

It will be understood that the system functions the same as above described when some station other than the end station has indications to transmit at the same time a station nearer the control office has new indications to transmit. Relay FBS⁴ at the end field station is picked up under this condition and the apparatus at the station nearest the end of the line functions in the same manner as just described in connection with the end station, while the apparatus at the station nearer the control office functions in the same manner as described in connection with the intermediate field station. Likewise, if more than two field stations have indications to transmit at the same time, only the one nearest the end will be effective while all others nearer the control office will be locked out in the same manner as explained in connection with the above example.

45 *End of indication cycle.*—The system goes through the "change to normal" period at the end of an indication cycle in substantially the same manner as at the end of a control cycle. When relay EP is dropped at the end of the fifth 50 "on" period to mark the end of the last "on" period and the beginning of the "change to normal" period, there is no stepping relay to be picked up for closing the energizing circuit for relay E which controls relay EP. Therefore, relays EP and E remaining down, maintain the line deenergized for a sufficiently long interval to allow relays SA and SAP to drop in sequence.

In addition to deenergizing the stepping relays and effecting the other circuit operations already 60 described in connection with the "change to normal" period of a control cycle, the stick circuit of relay OBS, IPT, and 2PT is deenergized at front contact 68 of relay SA, causing the return of these relays to their normal positions. Relay ST is deenergized at front contact 128 of relay 2V 65 and front contact 23 of relay OBS, as well as at front contact 138 of relay IPT.

70 Relay LO in the control office is picked up when relay F actuates its contact 55 to the left hand position in the manner previously described. The energizing circuit of relay EPT is opened at front contact 23 of relay OBS, which results in relay EPT being restored to its deenergized position. At the end field station relay FBS⁴ is dropped when 75 (+) potential is removed from stick conductor

178 at front contact similar to 194 of relay SA¹. Relay S¹ is dropped when (+) potential is removed from conductor 178.

The lock-out relays at the various field stations are picked up when the system reaches its normal condition by means of a circuit similar to that extending from (+), left hand contact 170 of relay F¹, back contact 172 of relay SA¹ and lower winding of relay LO¹, to (—). This circuit continues through front contacts 179 and 174 of relay LO¹ to the winding of relay LOP¹ for energizing this latter relay. The system is now in its normal condition in readiness for the start of another cycle, either for the transmission of controls or the transmission of indications.

In order to prevent the useless operation of the stepping relays at those stations not selected during a control cycle and at those stations not in connection with the communication line during an indication cycle, the stepping relay actuating circuit is open at front contact 256 of relay S¹ and front contact 257 of relay LO¹. This result is obtained during a control cycle because all lock-out relays except at the selected station are dropped and no relay similar to relay S¹ is up. During an indication cycle this result is obtained because only the relay similar to relay S¹ at that station which obtains access to the communication line is picked up and all lock-out relays are down.

Resistance units such as R¹ and R⁴ shown in Fig. 1, have a resistance value dependent upon the distance of the associated field station from the end field battery FB⁴. Since the line circuit during a portion of the initiating period of an indication cycle includes only the equipment up to the station nearest the end of the line which is transmitting, the resistor at such station is provided to equalize the current flow in the line circuit, in order that the proper current value may be maintained in the line relays during such initiating period. For example, resistance R⁴ will have a maximum value and the similar resistance units at successive stations nearer the control office are reduced in value at each station in accordance with the usual engineering practice.

Having thus described one specific embodiment of a centralized traffic controlling system, it is to be understood that the particular arrangements illustrated are merely typical of applicants' invention and are not intended to show the exact circuit design necessary to carry out the features of the invention, but have been selected to facilitate in the disclosure rather than to limit its scope and it is further desired to be understood that various modifications may be made and various adaptations and alterations may be applied to the specific form disclosed in order to meet the various problems encountered in practice and that the system may be varied in the number of field stations, the amount of apparatus installed at a particular field station and the number of steps provided for station selection as well as station registration, all without in any manner departing from the spirit or scope of the present invention except as limited by the appended claims.

What we claim is:—

1. In a remote control system, a control office, a plurality of field stations, a line circuit connecting said control office with said stations, means for intermittently energizing said line circuit from a source of current at a first one of said stations to provide a series of impulses, means at a second one of said stations for reversing the

- flow of impulse current over said line circuit between said second station and said control office, and means at said second station for varying the length of said impulses.
5. 2. In a remote control system, a control office, a plurality of field stations, a line circuit connecting said control office with said field stations, means for transmitting a plurality of series of current impulses of variable polarity in one direction over said line circuit, means for transmitting a plurality of series of current impulses of variable polarity and variable length in the other direction over said line circuit, and means for preventing the transmission of a series of impulses of variable polarity and variable length when a condition exists requiring the transmission of variable polarity impulses.
3. In a remote control system, a control office, a plurality of field stations, a line circuit connecting said control office with said stations, means for transmitting a series of stored outbound code messages from said control office to said stations over said line circuit, means for transmitting a series of inbound code messages from said stations to said control office over said line circuit, and means for preventing the transmission of an inbound message until all of said stored outbound messages have been transmitted, each of said outbound messages being composed of a plurality of impulses of current of variable polarity and each of said inbound messages being composed of a plurality of impulses of current of variable polarity and variable length.
4. In a remote control system, a control office, a plurality of field stations, a line circuit connecting said control office with said field stations, means for storing the condition that a plurality of series of outbound and inbound messages simultaneously await transmission over said line circuit, means for first transmitting one of said inbound messages over said line circuit to said control office, and means for thereafter transmitting the outbound messages over said line circuit before another of said inbound messages can be transmitted.
5. In a remote control system, a control office, a plurality of field stations, a line circuit connecting said control office with said field stations, means in said control office for applying a series of coded impulses to said line circuit, step-by-step mechanisms at said stations and means whereby they are operated through a cycle in synchronism by said series of impulses, a normally energized lock relay at each of said stations for controlling the selection of the respective station, means responsive to said series of coded impulses for continuing the energization of said lock relay at one of said stations during said cycle, and means for deenergizing said lock relays at all other stations at a predetermined step of said cycle.
6. In a remote control system, a control office, a plurality of field stations, a line circuit connecting said control office with said field stations, means at said control office for energizing said line circuit with a series of time spaced impulses of uniform length for transmitting messages to said stations, means controlled at each of said stations for energizing said line circuit with a series of time spaced impulses of variable length for transmitting messages from said stations to said control office, and means controlled by the energization of only a portion of said line remote from said control office for preventing more than one of said stations energizing said line with impulses of variable length at the same time.
7. In a remote control system, a control office and a plurality of stations connected by a line circuit, a transmitter at said office and a receiver at each of said stations, impulsing means for said transmitter, means for operating said impulsing means to cause said transmitter to apply a series of polar impulses to said line circuit, a normally energized station selecting relay at each of said stations for controlling the response of the associated receiver to said series of impulses, means for maintaining said relays in their energized condition during the transmission of said series of impulses irrespective of their polarity, and means controlled by the polarity of said impulses for maintaining only the station selecting relay at a single station in its energized condition after the transmission of said series of impulses.
8. In a remote control system, a control office and a plurality of stations connected by a line circuit, a transmitter at said office and a receiver at each of said stations, impulsing means for said transmitter, means for operating said impulsing means to cause said transmitter to apply a series of characteristic impulses to said line circuit, a normally energized station selecting relay at each of said stations for controlling the response of the associated receiver to said series of impulses, means for maintaining said relays in their energized condition during the transmission of said series of impulses irrespective of their character, and means controlled by the character of said impulses for maintaining only the station selecting relay at a single station in its energized condition after the transmission of said series of impulses.
9. In a remote control system, a control office and a plurality of stations connected by a line circuit, a transmitter at said office and a receiver at each of said stations, impulsing means for said transmitter, means for operating said impulsing means to cause said transmitter to apply a series of characteristic impulses to said line circuit the earlier part of said series comprising a station selecting code and the later part of said series comprising controlling impulses for the selected station, a normally energized station selecting relay at each of said stations for controlling the response of the associated receiver to said series of impulses, means for maintaining said relays in their energized condition during the transmission of said earlier impulses irrespective of their character, and means controlled by the character of said earlier impulses for maintaining only the station selecting relay at a single station in its energized condition during the transmission of said later impulses.
10. In a remote control system, a control office, a plurality of field stations, a line circuit connecting said control office with said field stations, means for intermittently energizing said line circuit from a source of current at one of said stations for providing a series of impulses, means at said stations for reversing the flow of impulse current over said line circuit between said stations and said control office, means at said stations for varying the length of said impulses, and means responsive to the polarity and length of said impulses for selectively registering said stations in said control office.
11. In a remote control system, a plurality of locations including a control office and a plurality of field stations, a line circuit connecting

said locations and normally energized with current of a distinctive character, mechanisms at said locations capable of being operated through a cycle of operations by intermittent energization 5 of said line circuit, means for intermittently and characteristically energizing said line circuit during an operating cycle from a source of current at one of said locations whereby a first series of characteristic impulses is provided, 10 means for intermittently and characteristically energizing said line circuit during said operating cycle whereby a second series of characteristic impulses is provided, means controlled by a change in the character of energization of said 15 normally energized line circuit for allotting said first series of impulses to said cycle, and means controlled by a comparatively long deenergization of said normally energized line circuit for allotting said second series of impulses to said 20 cycle.

12. In a remote control system, a plurality of locations including a control office and a plurality of field stations, a normally energized line circuit connecting said locations, step-by-step 25 mechanisms at said locations capable of being operated through a cycle of operations by impulses on said line circuit, means for intermittently energizing said line circuit with impulses of selected polarities during an operating cycle of 30 said step-by-step mechanism from a source of current at a first one of said locations whereby a first series of impulses of variable polarity is provided, means for intermittently energizing said line circuit with impulses of selected polarities 35 and selected durations during said operating cycle from a source of current at a second one of said locations whereby a second series of impulses of variable polarity and variable length is provided, means controlled by a change in the 40 polarity of said normally energized line circuit for allotting said first series of impulses to said cycle, and means controlled by a comparatively long deenergization of said normally energized line circuit for allotting said second series of 45 impulses to said cycle.

13. In a remote control system, the combination with a control office and a plurality of field stations connected by a line circuit, means for energizing said line circuit with a plurality of 50 normally long impulses of distinctive polarity separated by time spaces, means at said stations for deenergizing said line circuit to provide abnormally short impulses, relay means connected to said line circuit in said control office, means 55 responsive to combinations of long and short impulses in said line circuit for selectively operating said relay means to register one of said stations in said office, and means responsive to the polarity of said impulses for registering 60 another one of said stations in said office.

14. In a remote control system, a control office and a plurality of field stations interconnected by a normally energized line circuit, transmitting means at each of said stations for transmitting 65 a series of current impulses over said line circuit to said office, a source of current at a single one of said stations for energizing said line circuit from any transmitting station, a selecting relay at each of said stations, means at each station for 70 momentarily de-energizing said normally energized line circuit and for subsequently momentarily energizing only that portion of said line circuit which extends from the associated station to stations more remote from said office, 75 means responsive to said momentary de-energi-

zation and subsequent energization of said line circuit for controlling said selecting relay, and means controlled by said selecting relay for rendering the transmitting means at the associated station active. 5

15. In a remote control system, a control office and a plurality of field stations interconnected by a normally energized line circuit, transmitting means at each of said stations for transmitting a series of current impulses over said line circuit to 10 said office, transmitting means at said office for transmitting a series of current impulses over said line circuit to said stations, a source of current at a single one of said stations for energizing said line circuit from any transmitting station, a 15 source of current in said office for energizing said line circuit from said office, a selecting relay at each of said stations, means at each station for momentarily de-energizing said normally energized line circuit and for subsequently momentarily 20 energizing only that portion of said line circuit which extends from the associated station to a station more remote from said office, means responsive to said momentary de-energization and subsequent momentary energization of said 25 line circuit for controlling said selecting relay, means controlled by said selecting relay for rendering the transmitting means at the associated station active, and means for rendering the transmitting means at all stations inactive as long as 30 the condition exists requiring the transmission of impulses from said office over said line circuit.

16. In a remote control system, a plurality of locations including a control office and a plurality of field stations, a line circuit connecting said 35 locations and normally energized with current of a distinctive character, mechanisms at said locations capable of being operated through a cycle of operations by intermittent energization of said line circuit, means for intermittently and characteristically energizing said line circuit from a source of current at a first one of said locations 40 whereby said mechanisms are operated through a first cycle and a first series of characteristic impulses is provided, means for intermittently and characteristically energizing said line circuit from a source of current at a second one of said locations whereby said mechanisms are operated through a second cycle and a second series of 45 characteristic impulses is provided, means controlled by a change in the character of energization of said normally energized line circuit for operating said mechanisms through said first cycle, and means controlled by a comparatively long deenergization of said normally energized 50 line circuit for operating said mechanisms through said second cycle. 55

17. In a communicating system of the multiple impulse type, the combination with a line circuit connecting two locations, step-by-step mechanisms at said locations capable of being operated through a cycle of operations in response to a series of impulses transmitted over said line circuit irrespective of the polarity of said impulses, means including the step-by-step mechanism at one of said locations for transmitting a series of impulses over said line circuit whereby said mechanisms are operated through a cycle of operations in synchronism, means including the step-by-step mechanism at one of said locations for characterizing each of said impulses with either of two polarities and either of two lengths, and means including the step-by-step mechanism at the other of said locations distinctively 70 75

responsive to the composite of the polarity and the length of any one of said impulses.

18. In a communicating system of the multiple impulse type, the combination with a line circuit connecting two locations, step-by-step mechanisms at said locations capable of being operated through a cycle of operations in response to a series of impulses transmitted over said line circuit irrespective of the polarity of said impulses, means including the step-by-step mechanism at one of said locations for transmitting a series of impulses over said line circuit whereby said mechanisms are operated through a cycle of operations in synchronism, means including the step-by-step mechanism at one of said locations for characterizing each of said impulses with either of two polarities and either of two lengths, storing means selectively controlled by the step-by-step mechanism at the other of said locations and distinctively responsive to the composite of the polarity and the length of any one of said impulses, an electro-responsive device, and means controlled by said storing means for distinctively controlling said device in accordance with said composite of polarity and length of any one of said impulses.

19. In a communicating system of the multiple impulse type, the combination with a line circuit connecting two locations, step-by-step mechanisms at said locations capable of being operated through a cycle of operations in response to a series of impulses transmitted over said line circuit irrespective of the polarity of said impulses, means including the step-by-step mechanism at one of said locations for transmitting a series of impulses over said line circuit whereby said mechanisms are operated through a cycle of operations in synchronism, means including the step-by-step mechanism at one of said locations for characterizing each of said impulses with either of two polarities and either of two lengths, storing means selectively controlled by the step-by-step mechanism at the other of said locations and distinctively responsive to the composite of the polarity and the length of each of said impulses, a plurality of electro-responsive devices, and means controlled by said storing means for distinctively controlling said devices in accordance with said composite of polarity and length of said impulses.

20. In a remote control system, a control office, a plurality of field stations, a line circuit connecting said office with said stations, means for energizing said line circuit from a first source of current at said office, means for energizing said line circuit from a second source of current at one of said stations, means in said office for intermittently interrupting the energization of said line circuit from said first source of current to provide a first series of impulses and from said second source of current to provide a second series of impulses, means at each of said stations for reversing the direction of flow of impulse current of any impulse of said second series, means at each of said stations for varying the duration of flow of impulse current of any impulse of said second series, means controlled by said first series for transmitting messages one way between said office and said stations, and means controlled by the direction of flow of impulse current and the duration of flow of impulse current of said series for transmitting messages the other way between said office and said stations.

21. In a remote control system, a control office, a plurality of field stations, a line circuit connecting said office with said stations, means for energizing said line circuit from a first source of current at said office, means for energizing said line circuit from a second source of current at a first one of said stations, means in said office for intermittently interrupting the energization of said line circuit from said first source of current to provide a first series of impulses and from said second source of current to provide a second series of impulses, means at said first and at a second one of said stations for reversing the direction of flow of impulse current of any impulse of said second series, means at said first and said second station for varying the duration of flow of impulse current of any impulse of said second series, means controlled by said first series for transmitting messages one way between said office and said stations, and means controlled by the direction of flow of impulse current and the duration of flow of impulse current of said series for transmitting messages the other way between said office and said stations.

22. In a remote control system, a plurality of locations, a line circuit connecting said locations, means for energizing said line circuit from a first source of current at a first location, means for energizing said line circuit from a second source of current at a second location, means for intermittently interrupting the energization of said line circuit from said first source of current to provide a first series of impulses and from said second source of current to provide a second series of impulses, means at said first location for determining the polarity of each impulse of said first series in accordance with predetermined codes, means at said second location for determining the polarity and length of each impulse of said second series in accordance with predetermined codes, means at said first location responsive only to said second series of impulses, means at said second location responsive only to said first series of impulses, and means controlled by said first and said second series of impulses for transmitting coded messages between said locations.

23. In a remote control system, a plurality of locations interconnected by a stepping line circuit, means at a first one of said locations for impressing a plurality of series of time spaced impulses on said stepping line circuit, a step-by-step mechanism at said first location operable through a separate cycle for each of said series of impulses, means controlled by said mechanism for selecting two local channel circuits for each step, means for causing said mechanism to take one step for each impulse of a series, means at a second one of said locations for determining the character of certain of said impulses, means at said second location for determining the length of said certain impulses, means for distinctively energizing one of said channel circuits in accordance with the character of the impulse for that step, means for recording the length of said impulse for that step, means for storing the recorded length of said impulse during the succeeding time space, and means for distinctively energizing the other of said channel circuits in accordance with the stored length of said impulse.
